ABSOLUTE PERMISSIVE BLOCK SYSTEM
OF RAILWAY SIGNALING

Ralph R. Kemmerer, Swissvale, and Crawford E. Staples, Edgewood, Pa., assignors to The Union Switch & Signal Company, Swissvale, Pa., a corporation of Pennsylvania

Application April 3, 1941, Serial No. 386,632

29 Claims. (Cl. 246—33)

Our invention relates to absolute permissive block (A. P. B.) signaling systems for stretches of two-direction running railway track and it has special reference to systems of this character wherein all major functions of both wayside and cab signal control are performed without the aid of line wires and by means of coded energy that is transmitted through the track rails.

Generally stated, the object of our invention is to improve the organization and broaden the range of application of coded track circuit A. P. B. systems which use the "coded feed back" operating principle of Frank H. Nicholson Patent No. 2,021,944 (issued November 26, 1935) and which are exemplified by the following copending applications of common ownership herewith: (1) Serial No. 294,897 filed September 14, 1939, by Ralph R. Kemmerer; (2) Serial No. 315,801 filed January 26, 1940, by Crawford E. Staples; and (3) Serial No. 382,431 filed March 8, 1941, by Frank H. Nicholson.

A more specific object is to make an improved utilization of the principles of track circuit reset that are disclosed and claimed by: (1) a copending application Serial No. 386,642 filed April 3, 1941, by Robert M. Gilson; and (2) a copending application Serial No. 386,615 filed April 3, 1941, by Leslie R. Allison.

Another object is to make an improved application of certain train detecting and cab signal supply apparatus that is disclosed and claimed by a copending application Serial No. 383,571 filed March 15, 1941, by Ralph R. Kemmerer.

We shall describe one representative form of A. P. B. signaling apparatus that embodies our invention and shall then point out the novel features thereof in claims. This illustrative embodiment is disclosed in the accompanying drawings in which:

Figs. 1a to 1f, inclusive, are diagrammatic views which when placed end to end in the order named represent a stretch of two-direction running railway track that is equipped with A. P. B. signaling apparatus which incorporates our improvements;

Fig. 2 is a single line diagram showing the limits of track circuit control for each of the several wayside signals with which the single track stretch of Fig. 1 is equipped; and

Fig. 3 is a diagrammatic showing of cut location facilities which may be interposed between the ends of any of the track sections of Figs. 1b—1e.

In the several views of the drawings, like reference characters designate corresponding parts.

To facilitate description of the various circuit diagrams of these views it will be assumed that the left end thereof is west and the right end is east. Hence, train movements in the direction of from left to right will be spoken of as "east-bound" and movements in the direction of from right to left will be spoken of as "westbound."

Referring first to the composite diagram of Figs. 1a-1f, the improvements of our invention are there disclosed in a system of absolute permissive block (A. P. B.) signaling for a stretch of main line track 1—2 which extends from a west passing siding PS1 (Fig. 1a) to an east passing siding PS2 (Fig. 1f) and over which traffic may move in either direction. The usual insulated joints 3 divide the rails 1 and 2 of this stretch into the customary plurality of successive track sections I—II, II—III, III—IV, IV—V and V—VI and the rails of each of these sections form part of a coded track circuit combination later to be described.

The track and signal layout of Fig. 1

Wayside signals SE positioned at the section-dividing locations, I, III, IV and V govern the passage of eastbound trains into and through the single track stretch I—VI of Fig. 1. Of these eastbound devices, signals SEM and SES at the stretch west end I respectively control movements of eastbound traffic from the westwardly extending main track 1—2 into the stretch and from the siding track PS1 into the stretch. Device SES will, therefore, be designated as an "eastbound siding leaving" signal. By the same token device SEM might logically be called a "main line leaving" signal. For reasons later made evident, however, it will be referred to as the "eastbound headblock" signal.

Signals SEIII and SEIV at locations III and IV are the usual "eastbound intermediate" devices and will be so referred to throughout this specification. Signal SEV at location V has similar "intermediate" characteristics but because of admitting eastbound traffic into the passing zone which siding PS2 defines it will be termed an "eastbound siding entering" signal.

Other wayside signals SW positioned at the section-dividing locations VI, IV, III and II govern the passage of westbound traffic into and through the single track stretch VI—I of Fig. 1. Of these westbound devices, signals SWM and SWS at the stretch east end VI respectively control movements of westbound traffic from the eastwardly extending main track 1—2 into the stretch and from the siding track PS2 into the

stretch. Device SWS will, therefore, be designated as a "westbound siding leaving" signal. Even though device SWM might logically be called a "main line leaving" signal it will, for reasons of greater convenience, be referred to as the "westbound headblock" signal.

Signals SWIV and SWIII at locations IV and III are the usual "westbound intermediate" devices and will be so referred to herein. Signal SWII at location II has similar "intermediate" characteristics but because of admitting westbound traffic into the passing zone which siding PS1 defines it will be termed as a "westbound siding entering" signal.

In the track and signal layout of Figs. 1a-1f each of the sections I-II and VI-V of "headblock" track is relatively short and typically will have a length not exceeding two or three hundred feet. These headblock sections, together with the signals directly associated therewith, serve to increase the effectiveness of the directional protection that can be provided by an A. P. B. system wherein they are incorporated.

The "intermediate" sections II-III, III-IV and IV-V of the single track stretch are, however, of the relatively longer order which the requirements of train braking make necessary. For a system layout of the represented two intermediate location (III and IV) type, each of the three intermediate sections just named typically will have a length of from one to two miles. As the number of intermediate locations is increased this length may, of course, be decreased; as the number of intermediate locations is decreased the section length must, by the same token, be proportionately increased.

A better conception of these comparative headblock and intermediate section lengths may be gained from the single line track diagram of Fig. 2. In that diagram: (1) the A. P. B. track stretch I-VI of Figs. 1a-1f is reproduced at the left; (2) the complete passing zone VI-Ia which siding track PS2 defines is shown at the center; and (3) a second A. P. B. stretch Ia-VIa which duplicates the first stretch I-VI is represented at the right.

The Fig. 1 plan of A. P. B. signal control

The eastbound and westbound wayside signals SE and SW earlier described for the main line and passing siding tracks of Fig. 1 may, of course, be of any suitable form; as here shown each is of a well-known color light type which comprises three lamps G, Y and R. When selectively lighted these lamps respectively display the indications of green or "clear," yellow or "approach" and red or "stop."

Selecting the indication that each of these wayside signals displays are "home" and "distant" control relays H and D at the location of the signal. The relays in each of these control sets H-D carry contacts 5 and 6 which are included in the lamp energizing circuits for the associated signal. Those circuits, in turn, derive lighting current from any suitable local energizing source that is designated by the terminals "plus" and "minus."

Looking at any one of the system signals and its pair of control relays H-D, it will be seen that: (1) with relays H and D both picked up the "clear" lamp G of the controlled signal receives lighting current over front contacts 5 and 6; (2) with relay H picked up and relay D released the "approach" signal lamp Y is energized over front contact 5 and back contact 6; and (3)

with relay H released the "stop" lamp R receives lighting current over back contact 5.

In the complete A. P. B. system of Fig. 1 these indication selector relays H-D for the system wayside signals SE and SW are controlled in the manner which the track diagram of Fig. 2 shows. In that diagram the thin horizontal lines that are represented above and below the central track showing respectively are identified with the westbound signals SW and with the eastbound signals SE.

In all instances: (1) the heavy vertical bar at each signal location identifies the pair of horizontal control limit lines emanating therefrom with the signal at the bar location which is on the same side of the track as is the bar; (2) each "solid" limit line designates that the "home" control relay H for the line-identified signal is held picked up when all track sections spanned by that line are vacant; (3) each "dotted" limit line designates that the "distant" control relay D for the line-identified signal is held picked up when all track sections spanned by that line are vacant; (4) each limit-line arrow that points in the direction of the associated signal's traffic control (eastbound for each device SE and westbound for each device SW) designates the range within which a track section shunt will release the signal control relay (H or D) to which the arrowed line applies; and (5) each limit-line arrow that points against the direction of the associated signal's traffic control (westbound for each device SE and eastbound for each device SW) designates the range within which a track circuit shunt will release the signal control relay (H or D) to which the arrowed line applies.

The eastbound headblock signal SEM (at location I) may well be used to illustrate how the control limit diagram of Fig. 2 is read. For following moves (refer to the limit-line arrows which point eastwardly), Fig. 2 shows that the control range of this signal's H relay (device HEM at location II) extends as far east as location III and that the control range of the signal's D relay (device DE at location II) further extends to location IV; for opposing moves (refer to the limit-line arrows which point westwardly), Fig. 2 shows that the control range of each of the signal's H and D relays extends still further east to location VI, and thus embraces the entire A. P. B. stretch of Fig. 1.

When, accordingly, that entire stretch is vacant, Fig. 2 directs that both of the just named H and D relays be picked up and that signal SEM then show "clear." When, however, a westbound train (see the westwardly pointing limit-line arrows) occupies any portion of the track stretch VI-I, Fig. 2 directs that the named H and D relays both release and that the eastbound headblock signal SEM now show "stop," in the conventional directional protection manner.

When, moreover, an eastbound train (see the eastwardly pointing limit-line arrows) occupies either of sections I-II and II-III, Fig. 2 directs that the H relay for signal SEM be released and that the named signal again show "stop"; when the eastbound train vacates sections I-II and II-III by moving into section III-IV, Fig. 2 directs that the named D relay only be released and that signal SEM then show "approach"; and when the eastbound train has moved completely into section IV-V, Fig. 2 directs that the named H and D relays both pick up and that signal SEM once more show "clear." These latter actions

accord, quite obviously, with conventional principles of following protection.

Reading, by way of further example, the control limit diagram of Fig. 2 on the eastbound intermediate signal SEIV (at location IV), it will be seen that this signal: (1) should show "clear" whenever the track length IV-IIIa is vacant; (2) should show "stop" whenever a westbound train occupies track length IV-VI; (3) should show "approach" whenever a westbound train is in track length IV-VIa; (4) should show "stop" whenever an eastbound train occupies track length IV-VI; (5) should show "approach" after the eastbound train has moved on into track length VI-IIIa; and (6) should show "clear" when the eastbound train has moved further on past location IIIa.

From the foregoing it will accordingly be seen that the eastbound and westbound wayside signals SE and SW of the Fig. 1 track layout are organized into a traffic controlling system that is designed to offer all of the usual features of A. P. B. protection. When controlled in accordance with the track limit diagram of Fig. 2, these signals thus permit two or more trains to follow each other through portions of single track that are between passing sidings and at the same time they prevent a train from entering a single track stretch when that stretch is occupied by another train moving in the opposite direction.

For effecting this Fig. 2 form of A. P. B. signal control use is made of the coded trackway apparatus which the composite diagram of Figs. 1a-1f represents. This apparatus exactly duplicates that which the earlier mentioned Norfolk and Western A. P. B. installation employs and it enables substantially all of the usual signal control line wires to be eliminated from the system, as Fig. 1 indicates.

The coded track circuit portions of this control apparatus differ somewhat with the positioning of the circuited track sections in the stretch and for the Fig. 1 system these trackway facilities may be grouped into the following classes:

(1) Track circuit combinations for the "intermediate" sections II-III, III-IV and IV-V;

(2) Track circuit combinations for the "head-block" sections I-II and V-VI; and

(3) Track circuit combinations for "passing siding" sections such as are indicated at VI-Ia and VIa-I in Fig. 2.

The track circuit combinations for the intermediate sections II-III, III-IV and IV-V will first be considered. These combinations are broadly similar to those which the earlier named Nicholson application Serial No. 382,431 discloses and claims. Each includes two track circuits respectively identified with the two opposing directions of traffic and herein designated as "eastbound" and "westbound."

Both of these track circuits in each combination include the rails 1-2 of the particular track section with which the combination is identified; one is supplied from a given end of the section with "normal master" code energy which is of a character suitable for controlling wayside signals and train carried cab signals and which consists of "on" period pulses that are separated by "off" period intervals and that recur at one or another of a plurality of distinctive code frequencies; and the other normally is supplied from the opposite end of the section with "off" period pulses of "feed back" energy which is of a character suitable for registering whether the "normal master" pulses are or are not being transmitted through

the full section length. Upon interruption of such master energy transmission the feed back pulses supplied to that other circuit are replaced by "special master" code energy which consists of recurring pulses that are independently modulated at one or another of a plurality of distinctive code frequencies and that is of a character suitable for controlling wayside signals and train carried cab signals.

As each of these "intermediate" track circuit combinations includes the rails 1-2 of the circuited track section plus cooperating apparatus at each of the two section ends, it is believed that a full and complete understanding thereof will result from an examination of the equipment which the Fig. 1 system utilizes at the various locations of track section junction therein.

Apparatus at intermediate locations III and IV

As represented by each of Figs. 1c and 1d, the apparatus at each of the intermediate locations III and IV comprises: (1) the earlier described eastbound and westbound wayside signals SE and SW; (2) relays HE-HEP-DE which serve to select the indication that the eastbound signal SE displays; (3) an eastbound track relay TR which is incorporated into the "eastbound" track circuit for the eastwardly extending section (which signal SE guards) and which controls relays HE-HEP-DE in accordance with the frequency of recurrence of pulses of operating energy that are received from the east section rails; (4) relays HW-HWP-DW which serve to select the indication that the westbound signal SW displays; (5) a westbound track relay TRA which is incorporated into the "westbound" track circuit for the westwardly extending section (which signal SW guards) and which controls relays HW-HWP-DW in accordance with the frequency of recurrence of pulses of operating energy that are received from the west section rails; (6) a source BX-CX of alternating current energy which is incorporated into the "eastbound" track circuit for the westwardly extending section and which under the control of a coder relay CTP supplies the west section rails with recurring pulses of "normal master" code current; (7) a source BK-CK of alternating current energy which is incorporated into the "westbound" track circuit for the eastwardly extending section and which under the control of a coder relay RC supplies the east section rails with "off" period pulses of "feed back" energy at times and with independently modulated pulses of "special master" code energy at other times; (8) code transmitters 180CT and 75CT which under proper conditions operate the eastbound and westbound coder relays CTP and RC at either a 180 or a 75 pulse per minute code frequency; (9) eastbound and westbound directional stick relays ES and WS which form part of the directional protection scheme for the complete A. P. B. system; and (10) devices CCR and SCP which assure a prompt resetting of the track circuit combinations under all conditions of shunt removal therefrom.

The "eastbound-westbound" track circuit combination for section III-IV will serve to illustrate the organization and functioning of each and every one of the intermediate section combinations (II-III, III-IV and IV-V) in the Fig. 1 system. Examining the Figs. 1c-1d portion of the composite diagram, it will be seen that the "master" energy source BX-CX at the section 75 east end IV normally transmits "on" period pulses

of "normal master" code energy to the eastbound track relay TR at the section west end; that the combined "feed back" and "special" code energy source BK—CK at that west end III normally transmits "off" period pulses of "feed back" energy to the westbound track relay TRA at the section east end; that the eastbound intermediate signal SEIII at the section west end III is controlled by the eastbound track relay TR thereat through the medium of "home" and "distant" decoding relays HE and DE plus a home repeater device HEP; and that the westbound intermediate signal SWIV at the section east end IV is controlled by the westbound track relay TRA thereat through the medium of "home" and "distant" decoding relays HW and DW plus a home repeater device HWP.

From the Fig. 1 diagram it will be evident that each set of these decoding relays HE—DE and HW—DW is supplied with pick-up energy over a pole changing contact 8 of the controlling track relay and by way of a decoding transformer DT and that the decoding relays of the set have response characteristics of the usual "frequency code" type. That is, both relays in each set stay released when the controlling track relay (TR or TRA) fails to follow code; the "home" relay (HE or HW) picks up whenever the controlling track relay follows code of either a 75 or a 180 pulse per minute frequency; and the "distant" relay (DE or DW) picks up only when the controlling track relay follows code of the 180 pulse per minute frequency.

As the circuit diagrams further show, this selective response by the "distant" relays DE and DW is produced by frequency selective units 180DU that are interposed in the relay pick-up circuits in the usual manner, while the necessary rectification of the current which the decoding transformers DTE and DTW supply to the "home" relays HE and HW is effected by track relay contacts 9 arranged as disclosed and claimed by a copending application Serial No. 210,744 filed May 28, 1938 by Frank H. Nicholson et al., now U. S. Patent 2,237,788.

One way in which the track circuit combinations of our invention differ from those of the Nicholson application Serial No. 382,431 is in supplementing these "home" decoding devices HE and DE by the earlier mentioned repeater relays HEP and HWP. In manners later to be made evident those repeater relays perform essential functions: (1) in the control circuits for the system's directional stick relays ES—WS (later to be described); (2) in the control circuits for the system's reset aiding devices SCP (also later to be described); and (3) in certain other circuits of the complete A. P. B. organization.

Each repeater relay HEP and HWP is designed to have a pick-up delay of from 0.3 to 0.4 (or more) second; each of these relays has a pick-up circuit which includes a front contact 10 of the controlling decoding device HE or HW; the pick-up circuit for each HEP relay further includes a back contact 11 of the westbound directional device WS at the same location; each HWP pick-up circuit similarly includes a back contact 12 of the associated eastbound device ES; relay HEP is provided with a snubbing resistor 16 which produces a release delay of about 0.25 second; and relay HWP is provided with a first snubbing resistor 21 which produces a release delay of about 0.25 second and also with a second snubbing element 23 which, under released conditions

of a WS contact 65, increases this delay period to between 0.85 and 1.3 second.

It will thus be seen: (1) that with WS contact 11 closed at its back point, the eastbound device 5 HEP repeats each pick-up and each releasing action of the decoding relay HE by which it is controlled; and (2) that with ES contact 12 released, the westbound device HWP repeats each pick-up and each releasing action of the decoding 10 relay HW by which it is controlled.

In both instances the release delays earlier stated assure: (1) that the controlling relay HE (which itself must be somewhat slow in releasing) always will reach the back contact position 15 ahead of the controlled repeater HEP; and (2) that the controlling relay HW (which also is somewhat slow in releasing) always will reach the back contact position ahead of the controlled repeater HWP. In addition, repeater HWP's 20 supplemental snub path 25—65 allows relay HWP to be quicker releasing during westbound train moves than at other times (when westbound stick relay WS is released) and thereby combines the advantage of quick westbound response with 25 an immunity to false response during code period interchange actions (later to be described) of a reset aiding relay CCR at the opposite end of the section.

From Figs. 1c-1d it will also be evident that the 30 indication which eastbound intermediate signal SEIII displays is determined by west-end decoding devices HEP—DE through the medium of the earlier named contacts 5—6 and that the indication which westbound intermediate signal 35 SWIV displays is similarly controlled by east-end decoding devices HWP—DW. In each instance, quite obviously, the controlled signal shows: (1) "clear" when the associated track relay (TR or TRA) follows code at the 180 rate; (2) "approach" when the track relay follows code at the 75 rate; and (3) "stop" when the track relay fails to follow code.

Eastbound intermediate track circuits

45 Looking at the complete track circuit combination for section III—IV of Figs. 1c-1d, it will be seen that the "normal master" code energy which is supplied to the section rails from source BX—CX at east location IV is modulated or periodically interrupted under the coding control of code transmitters 180CT—75CT at that east location. The contacts 180 and 75 with which these and all other transmitters in the system are provided operate in conventional 50 manner in that they repeatedly pick up and release at the respective frequencies of 180 and 75 times per minute.

One or the other of these transmitter contacts 180—75 at location IV operates section III—IV's 60 master coder relay CTP over a local driving circuit which includes a conductor 13. This so-operated coder device CTP (and all other devices of like designation in the system) is provided with contacts 14—15 which, depending upon 65 which of the transmitter contacts 180 and 75 is included in its driving circuit, recurrently pick up and release at one or the other of the two code frequencies earlier named. When picked up these contacts 14—15 connect the rails of section 70 III—IV with source BX—CX and thereby produce a normal master "on" period; when released these contacts transfer the rail connection to track relay TRA and thereby produce a normal master "off" period. Included in both of the 75

connections just named is the usual track transformer TTE.

Assignment of the driving circuit for this location IV coder device CTP to one or the other of the code transmitter contacts 180-15 at the same location is controlled by the eastbound decoding relay HE for section IV-V to the east. Acting through the repeater relay HEP at location IV, that eastbound decoding relay utilizes contacts 17-18 of device HEF together with contacts 19-20 of associated devices ES and HWP to select between the transmitter contacts 180 and 15.

When (as Fig. 1d shows) devices HE-HEP at location IV are picked up, the control of coder relay CTP is assigned to transmitter 180CT and that coder relay then is caused to produce a "normal master" energy code consisting of 180 "on" period pulses per minute; when, however, the relay driving circuit is transferred to transmitter 75CT, relay CTP is caused to produce a normal master energy code consisting of 75 "on" period pulses per minute.

In flowing westwardly over the section rails to west location III, the recurring pulses of this "normal master" code energy (from source BX-CX) are impressed upon the master track relay TR by way of track transformer TTW, back contacts 22-23 of an impulse relay RC, and a rectifier 24. Under vacant section conditions, accordingly, this track relay TR is caused to pick up and release its contacts 8-9 in step with the operations of code producing contacts 14-15 of the east end relay CTP. By the associated decoding relays HE-DE-HEP that response is, in turn, translated into appropriate indication selections for the eastbound wayside signal SEIII.

Thus, if at least one signal-block section to the east of location IV is vacant, the driving circuit for location IV relay CTP will be assigned to the code transmitter contact 180, the pulses of "normal master" energy supplied to section III-IV will recur at the 180 code rate, the eastbound track relay TR at location III will respond at that 180 rate; the associated relays HE-HEP-DE will all be picked up, and the eastbound signal SEIII will now show "clear."

Should an advance eastbound train be in the signal-block section just east of location IV, the driving circuit for location IV's relay CTP will be assigned to the code transmitter contact 75, the pulses of "normal master" energy impressed upon section III-IV now will recur at the 75 code rate, the eastbound track relay TR at location III will respond at that 75 rate, the associated relays HE-HEP only will be picked up, and the eastbound signal SEIII will show "approach."

Should, finally, the advance train be in section III-IV, the eastbound signal SEIII will display "stop." This, of course, results from the usual deenergization of track relay TRA and the consequent release of eastbound decoding relays HE-DE at location III.

The "normal master" track circuit organization just examined for intermediate section III-IV is, therefore, effective to control both the eastbound wayside signal SEIII and train carried cab signals (not shown) in the usual automatic block system manner and when expanded into the complete A.P.B. system of Fig. 1 it thus provides the desired following protection for all eastbound train moves through the A.P.B. stretch.

Westbound intermediate track circuits

A corresponding control of the westbound wayside signals SW, and also of train carried cab signals (not shown), is effected through the "feed back—special master" track circuit apparatus that earlier was referred to as supplementing the "normal master" organization just described. For intermediate track section III-IV of Fig. 1, this apparatus includes the westbound track relay TRA at the section east end IV and the westbound track circuit source BK-CK at the section west end III. During the "off" periods of the west end received "normal master" code energy, the before mentioned coder relay RC at west location III connects this source with the section III-IV rails over the front points of its contacts 22-23 and thereby supplies those rails with the pulsed "feed back" energy by which the east end track relay TRA at location IV is operated.

This location III coder relay RC (and all other devices of like designation in the system) closely resembles a device which Herman G. Blosser Reissue Patent No. 21,783 (granted April 29, 1941) discloses at IR in a "coded feed back" track circuit combination for single direction running. When this relay RC is deenergized, contacts 22-23 thereof occupy the released position (shown in Fig. 1c) wherein the rails of section III-IV are connected with the east end track relay TR; when, however, suitable pick-up current is supplied to the relay these contacts pick up and transfer the rail connection to the east end supply source BK-CK.

Under vacant track conditions, this pick-up current is derived from an output winding 26 of the location III decoding transformer DTE and transmitted to relay RC through a transformer 27. The primary of this transformer is connected with winding 26 at all times; the secondary of transformer 27 is connected with the winding of relay RC over a front contact 28 of eastbound decoding relay HE, either a front contact 29 of the westbound directional stick relay 45 WS at location III or a front contact 30 of the westbound decoding repeater relay HWP for the section to the west of that location, and a conductor 36.

Relay RC responds only to "positive" polarity pick-up energy (which makes the right terminal of its winding positive with respect to the left terminal) and each release of the eastbound track relay TR causes decoding transformer DTE to induce in winding 26 a pulse of such positive polarity potential. When the just described secondary circuit for transformer 27 is complete, each of those positive pulses is transmitted to relay RC and produces a momentary pick-up on the part of contacts 22-23 thereof.

Such pick-up, as already pointed out, connects the rails of section III-IV with the west end source BK-CK over a circuit which includes the usual track transformer TTW at location III. This connection causes a short pulse of "feed back" energy to be supplied to those rails. Each of these pulses coincides, under the conditions just described, with an "off" period of the east end supplied "normal master" code and hence is transmitted over the section rails to the east location IV.

There each of the thus transmitted pulses of feed back energy is impressed upon the westbound track relay TRA. Such impression is by way of transformer TTE, back contacts 14-15 of device CTP and a rectifier 31; it causes, quite

obviously, this east end track relay TRA to pick up its contacts 8-9 in step with the "off" period pick-ups of the west end coder relay RC.

For the purpose of equalizing the pick-up and release times of the so operated westbound track relay TRA, its pick-up circuit is supplemented by a stick circuit which prolongs each of the relay pick-ups for the full duration of the "off" period during which the pick-up occurs. This stick circuit includes a back contact 33 of the master coder relay CTP and a front contact 34 of the track relay; it is supplied with energy over either a front contact 35 of the eastbound decoding relay repeater HEP for the next section to the east or the front contact 12 of the eastbound directional stick relay ES at location IV; and it functions in the same manner as that disclosed and claimed by Patent No. 2,172,893 which issued to Edward U. Thomas on September 12, 1939.

Such response by section III-IV's westbound track relay TRA to "off" period pulses of feed back energy received from the section west end III registers at the section east end IV the fact that pulses of "normal master" code energy there impressed upon the section rails are by those rails being transmitted completely through to and received at the west location III.

During such registration the westbound track relay TRA at location IV operates at the code frequency that is set by the "normal master" energy pulses with which section III-IV is supplied at that east location. Normally, therefore, the controlled westbound signal SWIV would be held at "clear" by the 180 "off" period pulses per minute of received "feed back" energy. As will become more evident later, however, such a holding is undesirable and to prevent it the pick-up circuit for the westbound "distant" relay DW at location IV is broken, under vacant track conditions, by a contact 37 of the eastbound decoding repeater HEP at the same location. Signal SWIV is, in consequence, normally held at "approach."

This "vacant stretch" holding does not, however, prevent signal SWIV from showing the desired advance traffic responsive indication upon the approach of a westbound train. Such approach releases relays HE-HEP at location IV and thereby discontinues (through the medium of directional protection facilities later to be described) all transmission of "normal master" energy pulses to the west location III. That discontinuance releases relays HE-HEP at location III and thereby causes the relay RC thereat to operate not as an impulse device for the supply of "feed back" pulses during the master code "off" periods but instead as a repeater for one of the west end code transmitters CT180 and CT75.

During such operation, the trackway energy supplied at west location III (from source BK-CK over front contacts 22-23 of device CR) is modulated independently of the master code being produced at east location IV. To designate this independently modulated energy the earlier announced term of "special master" code will be employed.

During these conditions of "special master" code supply, the driving circuit 36 for location III relay RC is set up over one or the other of front contacts 29 and 30 of devices WS and HWP at the same location, back contact 28 of the eastbound decoding relay HE at location III, conductor 32, and contact 18 of the repeater device HEP for that eastbound decoding relay. This

driving circuit includes selector contact 20 of the westbound decoding repeater relay HWP for the track section to the west of location III. When picked up (at a time when devices HE and HEP are both released) this selector contact assigns the driving circuit for relay RC to the code transmitter 180CT (contact 180) at the same location; when released (under released conditions of devices HE-HEP) it transfers the circuit connection to contact 75 of the code transmitter 75CT.

If at least one signal-block section to the west of location III is vacant, the control for location III relay RC will be assigned to the code transmitter contact 180, the pulses of "special master" energy supplied to section III-IV will recur at the 180 code rate, the westbound track relay TRA at location IV will respond at that 180 rate, the associated relay HW-HWP-DW will all be picked up (contact 37 is now released), and the westbound signal SWIV will now show "clear."

Should an advance westbound train occupy the signal-block section just west of location III, the control for location III relay RC will be assigned to the code transmitter contact 75, the pulses of "special master" energy impressed upon section III-IV now will recur at the 75 code rate, the westbound track relay TRA at location IV will respond at that 75 rate, the associated relays HW-HWP only will be picked up, and the westbound signal SWIV will show "approach."

Should, finally, the advance train be in section III-IV, the westbound signal SWIV will display "stop." This, of course, results from the usual deenergization of track relay TRA and the consequent release of both of the westbound decoding relays HW-DW at location IV.

The combined "feed back" and "special master" track circuit organization just examined for intermediate section III-IV is, therefore, effective to control both the westbound wayside signal SWIV and train carried cab signals (not shown) in the usual automatic block system manner and when expanded into the complete A. P. B. system of Fig. 1 it thus provides the desired following protection for all westbound train moves through the A. P. B. stretch.

Directional protection in the Fig. 1 system

In order that a train entering either end of the A. P. B. stretch of single track will automatically establish its own directional protection therethrough, the complete system of Figs. 1a-1f includes facilities whereby advancement of the leading vehicle of the train past the entering headblock location (I or VI of Fig. 1) successively conditions the opposing track circuits ahead in such manner as to set the signals for opposing traffic at "stop."

Aiding in this successive conditioning are the directional stick relays ES and WS that previously were referred to as forming a part of the equipment at each of the intermediate locations III and IV.

In the organization which Figs. 1c-1d illustrate, both of the relays in each ES-WS set are deenergized and stay released as long as the A. P. B. stretch of single track remains vacant. Upon movement of an eastbound train through the stretch the normally released eastbound relay ES at a given intermediate location picks up when the leading vehicle of the eastbound train first gets about 1000 feet from that location and so stays until the trailing vehicle of the train 75 clears the east end of the section of which the

given location marks the west end. Similarly, upon movement of a westbound train through the stretch the normally released westbound relay WS at a given intermediate location picks up only from the time that the leading vehicle of the westbound train first gets about 1000 feet from that location until the trailing vehicle of the train has cleared the west end of the track section to the immediate west of the location.

This Fig. 1 organization of the directional stick relays is the same as that which a copending application Serial No. 386,633 filed by us on April 3, 1941, discloses and claims. In that organization the two devices ES—WS at each intermediate location are provided with a transformer unit EWS which supplies pick-up current to one or the other of those devices upon each approach of a train.

Each of these intermediate-location units EWS has a primary winding 40 that forms part of: (1) the circuit through which "normal master" code energy is supplied to the westwardly extending track section upon the approach of an eastbound train; and (2) the circuit through which "special master" code energy is supplied to the eastwardly extending track section upon the approach of a westbound train.

Looking, for example, at unit EWS at location IV, it will be seen: (1) that the first named circuit extends from "normal master" source terminal BX, through contact 101 of a relay CCR, one or the other of contacts 180a and 15a of code transmitters CT180 and CT175, code selecting contacts 41—42 of relays HWP—HEP, the unit's primary winding 40, a series winding E of the unit, conductor 43, front contact 14 of device CTP, the primary of section IV—III's track transformer TTE and front contact 15 of device CTP back to "normal master" source terminal CX; and (2) that the second named circuit extends from "special master" source terminal BK, through one or the other of code transmitter contacts 180a—75a, the unit's primary winding 40, a series winding W of the unit, conductor 44, a back contact 45 of relay HE, front contact 22 of device RC, the primary of section IV—V's track transformer TTW and front contact 23 of device RC back to "special master" source terminal CK.

Inductively coupled with this primary winding 40 of each EWS unit is a secondary winding 38 which has induced therein a potential that is proportional to the rail-energizing current which winding 40 transmits. This secondary winding feeds into a full-wave rectifier 39 which renders the alternating current potential thereof unidirectional.

Description of the design and operating characteristics of these EWS transformer units and all cooperating circuits is fully given by our copending application Serial No. 386,633 and will not be repeated here. For purposes of understanding the A. P. B. system of the present application a brief examination of these EWS units and their associated ES—WS directional stick relays will, it is thought, prove sufficient.

For such examination attention will be directed to elements ES—WS—EWS at location IV of Fig. 1d. With both of the there adjoining track sections IV—III and IV—V unoccupied, the rail supply current that passes through unit EWS is insufficient to produce pick-up on the part of either of relays ES and WS. Under such conditions, moreover, the pick-up circuit for relay WS is broken at contacts 46—47 of devices

HE—HEP and the pick-up circuit for relay ES is broken at contacts 48—49 of devices HW—HWP. Under these vacant track conditions, therefore, the directional stick relays ES and WS at location IV both stay released, as shown.

When, however, an eastbound train comes into section III—IV, relays HW—HWP at location IV drop and thereby complete (over contacts 48—49) a pick-up circuit for location IV's eastbound directional relay ES. This circuit may be traced from the positive terminal of rectifier 39 through conductor 51, a back contact 52 of device WS, back contact 48 of device HW, back contact 49 of device HWP, front contact 47 of device HEP, conductor 53, the winding of relay ES and conductors 54—55 back to the negative terminal of rectifier 39.

At first the trackway current which the now shunted section III—IV draws through unit EWS is insufficient to pick up relay ES over the circuit just traced. As, however, the eastbound train nears location IV this current gradually rises and when the closeness of train approach is reduced to about 1000 feet, relay ES picks up. Further advances of the train toward location IV cause, in a manner which our copending application Serial No. 386,633 more fully explains, this picked up condition of relay ES to continue.

As the eastbound train advances past location IV, relays HE and HEP there at successively drop in the order named. By this action a contact 57 of device HE establishes for relay ES a stick circuit which continues that relay picked up as long as any part of the eastbound train remains in section IV—V. That stick circuit is completed before device HEP breaks the original ES energizing circuit by its release of contact 47; it may be traced from a positive supply terminal through back contact 57 of device HE, a front contact 58 of relay ES, an impedance 59, conductor 53, the winding of relay ES, and conductor 54 back to a negative supply terminal.

When the eastbound train leaves section VI—V, relays HE—HEP at location IV again pick up and respectively: (1) release the directional stick relay ES thereat by breaking its stick circuit at contact 57; and (2) condition relay ES for response to another eastbound train by setting up its pick-up circuit at contact 47.

Location IV's westbound directional stick relay WS will be seen to operate in a comparable manner. Upon entry of a westbound train into section IV—V a pick-up circuit for that relay is completed by the dropping of relays HE—HEP which accompanies that entry. That pick-up circuit may be traced from the positive terminal of unit EWS's rectifier 39 through conductor 51, a back contact 60 of device ES, back contact 46 of device HE, back contact 47 of device HEP, front contact 49 of device HWP, conductor 61, the winding of relay WS, and conductors 54—55 back to the negative terminal of rectifier 39.

At first the trackway current which the now shunted section IV—V draws through unit EWS is insufficient to pick up relay WS (over the circuit just traced). As, however, the westbound train nears location IV this current gradually rises and when the closeness of approach is reduced to about 1000 feet, relay WS picks up. Further advances of the train toward location IV cause, in a manner which our copending application Serial No. 386,633 more fully explains,

this picked up condition of relay WS to continue.

As the westbound train advances past location IV, relays HW and HWP thereat successively drop in the order named. By this action a contact 62 of device HW establishes for relay WS a stick circuit which continues that relay picked up as long as any part of the westbound train remains in section IV-III. That stick circuit is completed before device HWP breaks the original WS energizing circuit by its release of contact 49; it may be traced from a positive supply terminal through front contact 11 of relay WS, conductor 63, back contact 62 of device HW, an impedance 64, conductor 61, the winding of relay WS and conductor 54 back to the negative supply terminal.

When the westbound train leaves section IV-III, relays HW-HWP at location IV again pick up and respectively: (1) release the directional stick relay WS thereat by breaking its stick circuit at contact 62; and (2) condition relay WS for response to another westbound train by setting up its pick-up circuit at contact 49.

For enabling each eastbound train that enters the Fig. 1 stretch at the west end I thereof to deenergize the westbound track circuits in advance and thereby put the westbound signals SW for the stretch at "stop", each of the just described westbound directional stick relays WS is provided with a "knockdown" contact 29. This contact is included in the driving circuit of the westbound coder relay RC for the track section to the east and it therein parallels the earlier described contact 30 of the westbound decoding repeater HWP.

By preventing the advance eastwardly extending sections of the stretch from receiving "feed back" energy (from source BK-CK) during the passage of eastbound traffic through the stretch, these contacts 29-30 of the system relays WS-HWP provide eastbound directional protection of the customary character; in addition the contacts 29 assure that all westbound train moves through the stretch will provide their own following protection. More detailed examination of both of these actions will be undertaken later.

For enabling each westbound train that enters the east end of Fig. 1 stretch to deenergize the eastbound track circuits ahead and thereby put the eastbound signals SE for the stretch at "stop," each of the just described eastbound directional stick relays ES is provided with a "knockdown" contact 19. This contact is included in the driving circuit of the eastbound coder relay CTP for the track section to the west and it therein parallels the earlier described contact 11 of the eastbound decoding repeater HEP.

By preventing the advance westwardly extending sections of the stretch from receiving "normal master" 75 code energy (from source BX-CX) during the passage of westbound traffic through the stretch, these contacts 19-17 of the system relays ES-HEP provide westbound directional protection of the customary character; in addition the contacts 19 assure that all eastbound train moves through the stretch will provide their own following protection. More detailed examination of both of these actions will be undertaken later.

Reset aiding devices CCR and SCP

Under certain conditions the track circuit combinations for the intermediate sections

II-III, III-IV, and IV-V encounter difficulty in shifting from their westbound control supply of "special master" code energy back to their vacant section supply of "feed back" energy. Such a shifting action will be referred to as "resetting" and the problems which are incident thereto are in part solved by the inventions of the earlier named Gilson and Allison applications Serial Nos. 386,642 and 386,615.

As the Gilson and Allison specifications rather fully explain, these reset problems arise out of the fact that at times the pulses of "normal master" code energy which are supplied (from source BX-CX) to the east end of a section may coincide with and be opposed by the pulses of "special master" code energy that are supplied (from source BK-CK) to the west end of the same section.

Looking, by way of illustration, at section III-IV of the present application, it will be seen that a shunt placed across the rails of this section continuously releases both the eastbound and westbound track relays TR and TRA therefor; that this continuous release of track relay TR at location III transfers (at contacts 28 and 18 of devices HE-HEP) the control of west end coder relay RC from the track relay TR to one of the code transmitters 180CT-75CT at the same location; and that this transfer causes relay RC to be driven by one of the named location III transmitters for the purpose of supplying (from source BK-CK) pulses of "special master" code to the section west end. As long, quite obviously, as the section rails remain shunted the supply of these "special master" pulses continues.

Upon removal of the shunt from the rails, moreover, these recurring pulses of "special master" code energy continue to be impressed upon the section west end III and hence are transmitted over the section rails toward the east location IV. At that east location, meanwhile, the section rails also are supplied with recurring pulses of "Normal Master" code energy which flow over the rails toward the west location III. Due to the resulting clash of these oppositely flowing pulses, the "normal master" energy may be prevented from getting through to and operating the west end track relay TR and the "special master" energy may be prevented from getting through to and operating the east end track relay TRA.

This prevention falsely holds the sections' eastbound and westbound signals SE and SW at "stop" and is objectionable for other obvious reasons. As the Gilson and Allison cases point out, it is at its highest effectiveness when the energy pulses of the two oppositely flowing codes recur at the same frequency and fall directly in step with each other. Under various dephased conditions of the opposing pulses that effectiveness may decrease to the point of substantial disappearance.

Such, for example, is the case upon: (1) ordinary clearance of the section east end IV by an eastbound train; and (2) ordinary clearance of the section west end III by a westbound train. In each of these instances the energy pulses that are supplied to the train leaving end of the section recur at the 75 code rate, the energy pulses that are supplied to the opposite end of the section recur at the 180 code rate, and resetting is prompt because times frequently occur when the energy supplied to each end of the section can get

through to and operate the track relay at the opposite end thereof.

The mechanics of such self-effected reset are as follows. Falling in step with the "off" periods of the west-to-east flowing "special master" code, the east-to-west flowing pulses of "normal master" energy reach and operate track relay TR; that operation picks up eastbound decoding relay HE at location III; that pick-up transfers (at contact 28) the driving circuit for coder relay RC from code transmitter 180CT to impulse winding 26 of decoding transformer DTE; that transfer causes the coder relay RC to pick up upon each release of the track relay TR; and that action restores the track circuit combination to the desired "coded feed back" form of vacant section operation.

Under certain other conditions, however, the two "clashing" codes do have the same frequency of pulse recurrence and in that event reset of the track circuit may be objectionably delayed. As an example of such other conditions, consider the following situation.

With the track stretch initially vacant, a train comes into section III-IV not by way of either end thereof but at an intermediate point therein from a spur siding (not shown). The section to the east of location IV being vacant, the east end coder relay CTP is being driven by the east end transmitter 180CT and the section rails now are receiving (from east end source BX-CX) 180 pulses per minute of "normal master" code energy. The section to the west of location III also being vacant, west end coder relay RC then is being driven by west end transmitter 180CT and the section rails now also are receiving (from west end source BK-CK) 180 pulses per minute of "special master" code energy.

Should the train now leave section III-IV not by passing out of either end thereof but by way of the same spur siding (not shown) over which it entered, the pulses of 180 code energy that are fed to the section from opposite ends will either: (1) "interfit" and allow both the west and the east end track relays TR and TRA to be energized in a manner which produces immediate reset; or (2) "clash" and prevent each of these track relays from receiving operating energy from the opposite end of the section. It is in the latter event that one of the earlier stated problems of track circuit reset occurs.

This will be referred to as the problem of "initial" reset. In accordance with the Gilson invention this initial reset problem is solved by supplementing the code supply apparatus at one end of each circuited section by a code converter relay CCR which during and immediately following each shunt of the section rails recurrently interchanges the "on" and "off" periods of the coded energy which is impressed upon those rails at the converter location. Upon restoration of the section to its normal unshunted condition, this interchange disrupts any reset preventing coincidence of the "normal master" code energy pulses and the opposing (and still independently supplied) pulses of "special master" energy and thereby permits the normal master pulses to reach the track relay TR at the feed back section end. In responding in the usual manner that relay now discontinues the "special master" code energy, substitutes "off" period pulses of "feed back" energy therefor, and thereby restores the track circuit to the desired "coded feed back" form of vacant section operation.

In the complete A. P. B. system of the present invention, the west end of each of the intermediate track sections II-III, III-IV and IV-V is equipped with one of Gilson's code converter relays CCR. This relay carries contacts 100-101 which respectively are included in: (1) the "special master" code driving circuit (one or the other of code transmitter contacts 180-75 and back contact 28 of device HE) for the impulse relay RC at the same location; and (2) the primary energizing circuit (one or the other of code transmitter contacts 180a-75a and transformer winding 46) for the directional stick relay pick-up unit EWS at the same location.

When these contacts 100-101 are released (as shown), element 100 connects the RC relay driving circuit with the back point of whichever of the two transmitter contacts 180 and 75 is included in that circuit; when, however, contacts 100-101 are picked up the RC relay driving circuit is shifted to the front point of the selected transmitter contact. Each shift, therefore, in the position of contacts 100-101 causes the coder relay RC to interchange the "on" and the "off" periods of the "special master" code energy which is supplied to the west end of the associated track section.

The operating characteristics of these code converter relays CCR for the Fig. 1 track sections II-III, III-IV and IV-V preferably duplicate those of the correspondingly identified devices of the Gilson application. In that event the contacts 100-101 of each relay normally occupy one or the other of their two positions continuously. When, however, pulsed driving current is supplied to the operating mechanism or winding of the relay (for details see Gilson's Fig. 3) these contacts 100-101 then shift their position at intervals of every eight seconds.

Supplying each of these CCR relays with such pulsed driving current at proper times is an operating circuit which includes a contact 75b of the code transmitter 75CT at the relay location, a back contact 58 of the eastbound directional stick relay ES at the same location, and a back contact 57 of the eastbound decoding relay HE for the eastwardly extending track section. As in the Gilson organization, the purpose of the stick relay contact 58 is to prevent needless operation of the converter relay CCR during certain eastbound train moves.

Each just described converter relay CCR accordingly holds its contacts 100-101 continuously in the same position as long as either of the associated relays HE and ES is picked up. When, however, both of the named control devices HE-ES become released, the controlled relay CCR receives pulsed operating current over code transmitter contact 75b and the CCR contacts 100-101 thereby are caused then to shift their position every eight seconds.

In examining how each of these CCR relays assures a prompt "initial" reset of the track circuit that extends eastwardly therefrom, attention will, by way of illustration, be directed to device CCR at location III and to the track section III-IV with which that device is associated. Under vacant conditions of the Fig. 1 track stretch, the track circuit combination for this section III-IV is operating in the normal "coded feed back" manner; the eastbound directional stick relay ES at location III is released; the eastbound decoding relay HE at the same location is picked up; and the west end code

converter relay CCR for section III-IV is, in consequence, maintained inactive.

Assume, now, that the rails of section III-IV become shunted at a time when the section to the west of location III is vacant and when the section to the east of location IV also is vacant. This shunt drops the eastbound track relay TR at location III, and, by transferring (at back contacts 28 and 18) the driving circuit for coder relay RC to code transmitter 180CT at that location, causes 180 pulses per minute of "special master" code energy to be impressed upon the section rails at the section west end III.

The release of relay HE at location III which produced that transfer causes contact 57 to complete the operating circuit for the code converter relay CCR. That completion, in turn, allows recurring pulses of driving current to reach (over the front point of code transmitter contact 15b) device CCR and thereby causes that device to shift the position of its contacts 100-101 every few seconds. Each of these shifts effects, in the manner earlier explained, an interchange in the "on" and the "off" periods of the west end supplied (over contacts 22-23 of coder relay RC) "special master" 180 code.

At the east end IV of the section, meanwhile, the driving circuit for the master coder relay CTP continues to be assigned to code transmitter 180CT, and, in consequence, 180 pulses per minute of "normal master" code energy now also are impressed upon the rails of section III-IV.

Assume next that the rail shunt is removed from section III-IV by some method other than train movement out of one end of the section. The stated requirement might, for example, be met by passage of a train vehicle out of the section by way of a spur siding (not shown). At the instant of such shunt removal the pulses of east end supplied "normal master" 180 code energy are net and opposed by the pulses of west end supplied "special master" 180 code energy.

If, at that instant the "normal master" pulses fall in step with the "special master" "off" periods, the energy of those normal master pulses gets through to track relay TR at location III in the desired manner. In responding that relay discontinues (by picking up relay HE) the supply of "special master" code energy and substitutes "off" period pulses of "feed back" energy therefor. This substitution constitutes a resetting of the track circuit and restores the desired "coded feed back" form of vacant section operation thereto. Under that condition, of course, the now picked up relay HE at location III interrupts (at contact 57) the operating circuit for the west end code converter relay CCR and thereby restores that relay to its normally inactive state.

In the event, however, that the pulses of "normal master" 180 code energy initially do coincide with the opposing pulses of "special master" 180 code energy, then relay TR at location III remains continuously deenergized and the track circuit is prevented from resetting. Such prevention persists, however, only until the code converter relay CCR at location III next shifts the position of its contact 100-101.

By that shift the "special master" code "on" and "off" periods are interchanged to a positioning wherein the "normal master" "on" period pulses do fall within the "off" period intervals of the opposing special master code. In

consequence, the energy of those master pulses now gets through to and operates the eastbound track relay TR at location III. That operation, in turn, initiates the before described series of actions by which the desired "initial" reset of track circuit III-IV is effected.

A second problem of reset which track circuit combinations of the section II-III and III-IV type must overcome arises out of the effect on a particular section of actions which take place in one of the adjoining sections of the A. P. B. stretch. This effect is to be distinguished from the "initial" reset functions which the just described code converter relays CCR perform and it results in what will be termed a "cascading" of the reset operation requirement from one section to another.

As the Allison application Serial No. 386,615 very clearly brings out, such cascading is peculiar to A. P. B. systems wherein track circuits of the type herein considered are included and in the absence of cascade preventing means the attendant section-to-section transfer of the reset requiring conditions may in certain cases cascade itself back and forth from one end of the A. P. B. stretch to the other several times before permanent reset is effected.

In accordance with the Allison invention this cascading difficulty is overcome by: (1) supplementing the "normal master" code supply apparatus of each "cascadable" track section in the A. P. B. stretch by an auxiliary device FL or BL (not shown herein) which when operated makes a single interchange in the "on" and "off" periods of the "normal master" code energy that is supplied to the section rails at the device location; and (2) arranging that this device will delayedly operate in response to each restoration of the location adjoining track section to its normal "coded feed back" form of vacant section operation.

In the track circuit combinations of our complete A. P. B. system Allison's just described "code period interchange" devices (FL or BL) are replaced by auxiliary relays SCP. One of these relays is installed at the east end of each of the intermediate track sections II-III and III-IV and it there performs functions similar to those of the Allison device plus certain additional ones later to be made evident.

In the form shown at each of locations II and III, this auxiliary relay SCP carries a pair of contacts 67-68 which normally are released, as Fig. 1 illustrates. Under that condition, quite obviously, the master coder device CTP at the relay location is free to repeat the coding action of one of the associated code transmitters 180CT-75CT and pulses of "normal master" code energy then are supplied to the rails of the westwardly extending track section in the before described manner.

Under certain other conditions, however, each of these auxiliary relays SCP has completed therefor a pick-up circuit which may be traced from a positive supply terminal, through front contact 57 of device HE at the relay location, conductor 69, front contact 70 of device HW, contacts 71 and 72 of devices HWP and HEP, conductor 73 and the winding of relay SCP back to the negative supply terminal.

Each such completion picks up the SCP relay and thereby causes: (1) contact 67 to connect the associated master coder relay CTP directly with the "plus" terminal of its control source; and (2) contact 68 to connect the front point of

this CTP relay's contact 14 directly with terminal BX of the "normal master" trackway source. During these connections: (1) relay CTP is held continuously picked up; and (2) source BX-CX supplies the rails of the westwardly extending track section with uncoded or steady "normal master" energy.

As will become more evident presently, this steady energy persists for a time which while relatively short, substantially exceeds the longer "off" period of any of the trackway codes for the A. P. B. system. Each supply thereof may, therefore, be characterized by the term of "single code pulse." Typically, each such pulse will have a duration in excess of 0.4 second and is, of course, terminated by the release of the controlling relay SCP.

Before examining when and for what purpose these auxiliary relays SCP pick up and release, it may be pointed out that two important functions are performed by the just described "single code pulse" energy that the relays govern. These functions are: (1) prevention of reset "cascading" from one A. P. B. track section to another; and (2) making more prompt and positive the "initial" reset of track circuit combinations for individual sections in the system.

The last named function will be considered first. To explain it the track circuit combination for section III-IV will again be examined. In this combination (and in all others of corresponding intermediate character), the earlier discussed west end code converter relay CCR at location III is supplemented by the "single code pulse" relay SCP that is installed as just described at the section east end IV.

That supplement, however, in no way interferes with the earlier explained functioning of the west end relay CCR; whenever devices HE and ES at location III both are released that relay shifts its contacts 100-101 at intervals of about eight seconds and by thus interchanging the "on" and "off" periods of the "special master" code energy that is supplied to the west end of the section it assures an "initial" reset of track circuit III-IV sometime within the eight second interval.

What the supplementing relay SCP at the section east end IV does do is to: (1) pick up upon the first response of the westbound code detecting relay HW thereat to either "special master" code or "feed back" energy that is received from the section west end III; and (2) impress "single code pulse" energy upon the section east end during such pick-up. This pick-up by relay SCP is produced in the following manner.

At the instant of the named HW relay response, the westbound code detecting and repeater relays HW and HWP at location IV both are released (assuming that section III-IV previously was shunted) while the eastbound code detecting and repeater relays HE and HEP at the same location both are picked up (assuming that section IV-V now is vacant). As the first pulse of BK-CK energy from the west reaches track relay TRA at location IV and picks up the associated relay HW, contact 10 of that relay HW picks up and is followed about 0.4 second later by a pick-up of contact 11 of slow responding repeater relay HWP. During that 0.4 second interval the reset aiding relay SCP is picked up over front contacts 51 and 10 of relays HE and HW, back contact 11 of relay HWP and front contact 12 of relay HEP.

While so picked up, relay SCP causes "single code pulse" energy to be impressed upon the east end of section III-IV. The duration of that steady energy impression (in excess of 0.4 second as aforesaid) is sufficient to overlap a full "off" period of any opposing code (either "special master" or "feed back") that is supplied to the section west end III. During that overlapped "off" period the single pulse energy from the east location IV reaches west location III without interference and there provides a very positive pick-up for the eastbound track relay TR.

That positive pick-up by the west end track relay TR may occur before, during, or after the "initial" resetting of track circuit III-IV which the code converter relay CCR therefor by itself effects. When before, it independently transfers (at contact 28) the control for location III's coder relay RC to the impulse transformer 27 and thereby provides positive reset more quickly than could relay CCR; when during, it guards against a subsequent reset loss due to too weak an original pick-up of relay TR and thus renders the initial reset more positive and lasting; and when after, it in no way interferes with the earlier restored "coded feed back" form of vacant section operation for track circuit III-IV.

The function of the auxiliary relays SCP in preventing "cascading" of the reset operation requirement from one section to another will next be considered.

One pressing need for such prevention is encountered during eastbound train moves through the A. P. B. stretch. Assume, for example, that an eastbound train which entered the stretch of Fig. 1 at the west location I has advanced to the point in the stretch where it is about to leave the east end of section IV-V.

While the train is at this point, relay ES at location IV is up; relays HE-HEP at the same location are down; and the east end of section III-IV is being supplied with "normal master" code energy. This supply results from the master coder relay CTP at location IV being driven by one of the code transmitter contacts 180-75 at the same location over a connection therewith which includes front contact 19 of relay ES.

As, now, the train moves out of section IV-V, relay HE at location IV picks up; relay ES at the same location very quickly releases; and after a delay of about 0.4 second relay HEP picks up. During this delay interval the driving circuit for the master coder relay CTP at location IV is broken at the as yet unpicked up contact 11 of relay HEP.

That breaking, quite obviously, may happen to fall at any point in the cycle of "normal master" code for section III-IV that relay CTP is producing. If it falls at the beginning of an "off" period, the interval of no energy supply is extended only slightly beyond 0.4 second. This extension not greatly exceeding the "off" period length for 75 code, no objectionable effects are produced at location III.

If, however, the CTP driving circuit break (by contact 19) occurs at the very end of a normal master "off" period, the interval during which no energy is supplied to the east end of section III-IV equals the "off" code period time plus the 0.4 second pick-up delay for relay HEP. At location III the resulting prolonged release of track relay TR allows eastbound code detecting relay HE to drop its contacts. Even though

momentary, the duration of this drop proves sufficient to effect the release of repeater HEP.

By that release contact 11 breaks the driving circuit for the master coder relay CTP at location III and thus causes the track circuit combination for section II-III to lose its reset; and by a similar sequence of actions succeeding intermediate track sections (not shown in Fig. 1) that may lie to the west of location II are caused to lose their reset. Such reset losses, of course, falsely put the associated eastbound signals SE at "stop" and for other obvious reasons they are highly objectionable.

To eliminate that cascading of reset loss through the westwardly extending track circuits, use is made of our earlier described "single code pulse" relays SCP at the intermediate section east ends. Again examining device SCP at location IV, its functioning upon the earlier described eastbound train movement out of sections IV-V will now be reviewed.

As the train clears location V, "normal master" code energy is again transmitted to location IV. There track relay TR responds and picks up eastbound code detecting relay HE. At the instant of this pick-up by relay HE, the westbound code detecting relay HW at location IV is picked up (assuming that section III-IV was originally reset) and the eastbound decoding repeater HEP at the same location is released (due to the previous shunt of section IV-V).

Hence, the original pick-up by contact 51 of this location IV relay HE is followed about 0.4 second later by a pick-up of contact 71 of the associated slow acting repeater relay HEP. During that 0.4 second interval the location IV relay SCP is picked up over front contacts 51 and 70 of relays HE and HW and back contact 72 of relay HEP.

While so picked up, relay SCP causes "single code pulse" energy to be impressed upon the east end of section III-IV. The duration of that steady energy impression (in excess of 0.4 second as aforesaid) is sufficient to overlap a full "off" period of any opposing code (either "special master" or "feed back") that is supplied to the section west end III. Its effect is (as before) to provide a very positive pick-up for the west end track relay TR.

That positive pick-up by track relay TR at location III guarantees that the track circuit combination for intermediate section III-IV will under no circumstance lose its reset upon the earlier described departure of an east-bound train from the adjoining intermediate section IV-V to the east. A similar guarantee against loss of reset in the intermediate sections to the west of section III-IV is, in turn, made by the "single code pulse" relays at the east ends of those west sections.

From the illustrative condition of reset loss "cascading" which has just been described it will be seen that the "single code pulse" relays SCP of the Fig. 1 system effectively safeguard each and every intermediate track section therein from having its "coded feed back" form of vacant section operation objectionably interfered with by actions which take place in one of the adjoining sections.

Such further tendencies (not described herein) toward reset cascading as may be set up during operation of the complete A. P. B. system are found also to be overcome by the novel reset aiding facilities of our invention. In the earlier mentioned Norfolk and Western's commercial in-

stallation of those facilities all reset problems seem, in fact, to have been successfully solved thereby.

Apparatus for west headblock section I-II

Description now having been given of the intermediate location positions of our new and improved A. P. B. system, attention will next be directed to the two headblock track sections I-II and V-IV which the complete system of Figs. 1a-1f comprises. The apparatus for the west headblock section I-II of Figs. 1a-b will first be examined.

This apparatus comprises: (1) eastbound "headblock" and "siding leaving" signals SEM and SES earlier described as being installed at location I; (2) westbound "siding entering" signals SWII earlier described as being installed at location II; (3) "home" relays HEM and HES for respectively controlling signals SEM and SES; (4) a "distant" relay DE which aids in the control of both of those signals; (5) "home" and "distant" control relays HWI and DW for signal SWII; (6) track circuit and associated wayside facilities for governing the just named signal control relays in accordance with traffic conditions in and beyond the ends of section I-II and for supplying cab signal control energy to the rails of that section; (7) a track switch W for selectively connecting the rails of passing siding PS1 with those of the main track 1-2; (8) switch repeater relays NWP-RWP for causing the signal control relays to check and respond to changes in the position of switch W; and (9) code transmitters 180CT and 75CT which form a part of the track circuit facilities for headblock section I-II and which also are utilized by the track circuit facilities for the east and west adjoining sections.

The earlier described shortness of this west headblock section I-II (length seldom greater than two or three hundred feet) permits devices at either of the two section ends very readily to be connected with opposite end devices over line or cable wires and in the composite diagram of Figs. 1a-b a number of such connections are illustrated.

The track circuit portions of the complete signal control combination which is represented by that diagram comprise: (1) apparatus connected with the west end II of the eastwardly adjoining track section II-III; (2) apparatus connected with the east end I of the westwardly adjoining section (which corresponds to Ia-VI of Fig. 2); and (3) apparatus connected with the rails of headblock section I-II.

Looking first at the location II apparatus for track circuit II-III, that apparatus will be seen to comprise elements TTW, RC, BX-CX, TR, DTE, HE, DE, 180-75CT and CCR which are organized in substantially the same manner as at each of locations III and IV (for sections III-IV and IV-V).

The manner in which these location II devices operate is so similar to that earlier described for the corresponding devices at the east ends of track circuits III-IV and IV-V that no detailed explanation of such operation will now be repeated. Instead it will suffice to observe: (1) that the code-selector contacts 18-20 and 42-44 for the "special normal" energy (from source BK-CX) control and supply circuits 32 and 44 are carried by the "home" and "distant" control relays HWI and DW for the siding entering signal SWII; and (2) that the eastbound directional

protection contact 30 of the RC relay driving circuit 36 is carried by a repeater device CDP for a code detector relay CD.

Looking next at the location I apparatus for the westwardly extending track circuit I-VI (which spans passing siding PS1), that apparatus will be seen to comprise elements TTE, CTP, BX-CX, TRA, DTW, HW, HWP and 180-75CT which are organized in substantially the same manner as at each of locations IV and III (for sections IV-III and III-IV).

The manner in which these location I devices operate is so similar to that earlier described for the corresponding devices at the west ends of track circuits IV-III and III-II that further explanation of such operation is not believed necessary.

Instead it will suffice to observe: (1) that coding of the "normal master" energy (from source BX-CX) control and supply circuits 13 and 43 is effected by contacts 180b-75b and 180c-75c of the transmitters 180CT-75CT; (2) that the function of code selection in these circuits is effected by contacts 11 and 18 of the "home" control relay HEM for the eastbound headblock signal SEM; (3) that the driving circuit 13 for coder relay CTP further includes contacts 17-104-105-106 of devices CDP, HWP, HW and RWP; (4) that the supply circuit 43 for transformer TTE may at times be connected with source terminal BX over contacts 109 and 110 of relays HWP and HW; (5) that the pick-up circuit 10 for relay HWP is carried over one or the other of front contacts 14 and 19 of devices CDP and RWP; and (6) that the hold-up prolonging circuit for track relay TRA is carried over contacts 16 and 91 of devices CDP and RWP.

Coming now to the track circuit apparatus for the headblock section I-II, that apparatus will be seen to comprise: (1) track transformers TTE and TTW at the east and west ends of the section; (2) a series transformer TU connected in the rail circuit of device TTW; (3) track and detector relays TR1 and CD energized from transformer TU through a rectifier 81 over front contacts 82-83 of a coder relay CTP1 and by-passed at the back point of contact 82; (4) a driving circuit 84 for this coder relay which at times supplies the relay winding with pulsed pick-up current from code transmitter contacts 180b-75b over code selector contacts 85 and/or 86 of devices DE and DW and which at other times supplies the winding with steady pick-up current from back contacts 87 and/or 88 of devices HE and HW over selector contacts 89 and 90 of relays CD and WVS; (5) an energizing circuit 92 for transformer TTE which under all vacant section conditions supplies the transformer with coded current from source BX-CX over front contact 93 of coder relay CTP1 and which under occupied section conditions supplies the transformer with steady energy over front contact 94 of relay WVS; and (6) a combined energizing and shunting circuit 95-98 for transformer TTW which normally by-passes the transformer primary through back contact 96 of device WVS but which at times supplies the transformer with "on" period pulses of coded current (from source BX-CX) over back contact 93 of device CTP1 and front contact 96 of device WVS while establishing "off" period by-passes for the transformer primary at contact 97 of device CTP1.

The just described combination of track circuit apparatus for headblock section I-II is

basically the same as that which the earlier identified copending Kemmerer application Serial No. 383,571 discloses and claims (see Kemmerer's Fig. 2).

5 In that combination track section I-II functions as a "detector" length of track. Under all vacant conditions thereof, 180 code supplied to the east end over front coder contact 93 and transformer TTE is transmitted by the section rails to west end transformer TU (TTW is shorted at contact 96) and impressed (through rectifier 81 and front contacts 82-83) upon relays TR1 and CD. Those relays are, in consequence, held picked up until a train enters one of the two section ends.

When such entry is at location I by an eastbound train, the supply of coded energy to east end transformer TTE continues but the driving circuit 84 for coder relay CTP1 becomes assigned, by contact 89 of the now released detector relay CD, to code selector contacts 87-85 of the eastbound traffic responsive relays HE-DE for the eastwardly extending section II-III. In consequence, the east end of section I-II now receives: (1) 180 code energy if at least two sections to the east of location II are vacant; (2) 75 code energy if only the first of those sections is vacant; and (3) steady energy (over back contact 87) if section II-III is occupied. This energy, quite obviously, is suitable for controlling cab signals which the eastbound train may carry.

When, at some other time, a westbound train enters section I-II at the east end thereof: (1) the westbound transformer TTW is at once 35 conditioned to supply coded energy to the west end I of the section; and (2) the driving circuit 84 for coder relay CTP1 becomes assigned to code selector contacts 88-86 of the westbound traffic responsive relays HW-DW for the track to the west of location I. These two actions are respectively effected by a picking up of contacts 96 and 90 of relay WVS.

40 That pick-up, in turn, is produced by the train effected release of relay CD's back contact 99 and it takes place over back contact 10 of device HE, front contact 108 of device HW1 and back contact 99 of device CD. Once effected it is prolonged by the completion at contact 111 of relay WVS of a stick circuit which includes contacts 112 and 99 of devices NWP and CD.

45 As a result of the above stated actions the west end of section I-II now receives: (1) 180 code energy if at least two sections of track to the west thereof are vacant; (2) 75 code energy if only one of those sections is vacant; and (3) steady energy (over back contact 88) if the section adjoining location I is occupied. This energy, quite obviously, is suitable for controlling cab signals which the westbound train may carry.

50 Looking finally at the remaining equipment for the west headblock section I-II, it will be seen: (1) that the repeater relay NWP for the track switch W is picked up over back contact 114 of device RWP and supply terminal contacts 115-116 when and only when switch W keeps the rails of passing track PS1 completely disconnected from those of the main line track I-2; (2) that the companion relay RWP is picked up over back contact 117 of device NWP and the supply contacts 115-116 when and only when switch W establishes the siding rail connection just named;

55 (3) that the repeater relay CDP for detector device CD is governed solely by front contact 118 of that device circuit and has slow pick-up charac-

teristics; (4) that the "home" control relay HEM for signal SEM at proper times receives pick-up energy over front contact 10 of device HE, front contact 120 of device CDP, front contact 121 of device NWP, and back contact 122 of device HES; (5) that the pick-up circuit for signal SES's "home" control relay HES includes front contacts 10 and 120 of devices HE and CDP, front contact 123 of device RWP, and back contact 124 of device HEM; (6) that the pick-up circuit for signal SWII's "home" control relay HWI includes front contact 126 of device HWP, front contact 127 of device CDP, and front contact 173 of device NWP; and (7) that signal SWII's "distant" control relay DWI is provided with a line-wire control circuit 128-129 which spans the entire length of passing siding PS1 and which terminates in contacts 130-131 of an HWM relay (see Figs. 1e and 1f) at the west end of that passing siding.

The reason for this line-wire control circuit 128-129 will be made clear through a later examination of the control limit diagram of Fig. 2 and of the "complete system" operation which that diagram summarizes.

Apparatus for east headblock section V-VI

The equipment for the west headblock section I-II now having been examined, attention will next be directed to the corresponding apparatus for the east headblock section V-VI.

From the composite diagram of Figs. 1e-f this apparatus will be seen to comprise: (1) westbound "headblock" and "siding leaving" signals SWM and SWS earlier described as being installed at location VI; (2) eastbound "siding entering" signal SEV earlier described as being installed at location V; (3) "home" relays HWM and HWS for respectively controlling signals SWM and SWS; (4) a "distant" relay DWI which aids in the control of both of those signals; (5) "home" and "distant" relays HEP and DE for controlling signal SEV; (6) track circuit and associated wayside facilities for governing the just named signal control relays in accordance with traffic conditions in and beyond the ends of section V-VI and for supplying cab signal control energy to the rails of that section; (7) code transmitters 180CT and 15CT which form part of those headblock section facilities and which also are utilized by the track circuits for the west and east adjoining sections; (8) a track switch W for selectively connecting the rails of passing siding PS2 with those of the main track 1-2; and (9) switch repeater relays NWP-RWP for causing the signal control relays to check and respond to changes in the position of switch W.

Like the west section I-II, this east headblock section V-VI is so relatively short (length seldom greater than two or three hundred feet) that devices at opposite ends thereof may readily be interconnected through line or cable wires and in the composite diagram of Figs. 1e-f a number of such connections are illustrated.

The track circuit portions of the complete signal control combination of that diagram will first be examined. These portions comprise: (1) apparatus connected with the east end V of the westwardly adjoining track section V-IV; (2) apparatus connected with the west end VI of the eastwardly adjoining section (which corresponds to VI-Ia of Fig. 2); and (3) apparatus connected with the rails of the headblock section V-VI of Figs. 1e-f.

Looking first at the location V apparatus for track circuit V-IV, that apparatus will be seen to comprise elements TTE, CTP, BX-CX, TRA, DTW, HW, HWP and 180-15CT which are organized in substantially the same manner as at each of locations IV and III (for sections IV-III and III-II). These location V devices operate in a way which is so similar to that earlier described for the corresponding devices at the west ends of track circuits IV-III and III-II that no further explanation of such operation is now believed necessary.

Instead it will suffice to observe: (1) that coding of the "normal master" energy (from source BX-CX) control and supply circuits 13 and 43 is effected by contacts 180b-75b and 180c-75c of the transmitters 180CT-15CT; (2) that the function of code selection in these circuits is effected by contacts 56-77 and 66-78 of the control relays HEP and DE for the eastbound siding entering signal SEV; (3) that the driving circuit 13 for coder relay CTP further includes contacts 11-104-105-106 of relays CDP, HWP, HW and XVS; (4) that the CDP contact 17 in this circuit takes part in establishing westbound directional protection; (5) that the supply circuit 43 for transformer TTE may at times be connected with source terminal BX over contacts 109 and 110 of relays HWP and HW; (6) that the pick-up circuit 10 for relay HWP is carried over contact 74 of device CDP; and (7) that the hold-up prolonging circuit for track relay TRA is carried over contacts 76 and 91 of devices CDP and XVS.

Looking next at the location VI apparatus for the westwardly extending track circuit VI-I (which spans passing siding PS2), that apparatus will be seen to comprise elements TTW, RC, BK-CK, TR, DTE, HE, DE, 180-15CT and CCR which are organized in substantially the same manner as at each of locations III and IV (for sections III-IV and IV-V).

These location VI devices operate in a way which is so similar to that earlier described for the corresponding devices at the east ends of track circuits III-IV and IV-V that no further explanation of such operation is now believed necessary. Instead, it will suffice to observe: (1) that the code selector contacts 20 and 41 for the "special normal" energy (from source BK-CK) control and supply circuits 32 and 44 are carried by the "home" control relay HWM for the westbound headblock signal SWM; (2) that the supply circuit 44 for transformer TTW further includes contacts 133-134-135-136 of devices RWP, VSP and ADW; and (3) that the driving circuit 28-36 for coder relay RC further includes contacts 155-156-157-158-159-160 of devices RWP, CDP, VSP, ADW and HWP.

Coming now to the track circuit apparatus for the headblock section V-IV, that apparatus will be seen to comprise: (1) track transformers TTE and TTW at the east and west ends of the section; (2) a series transformer TU connected in the rail circuit of device TTE; (3) track and detector relays TR1 and CD energized from transformer TU through rectifier 81 over front contacts 82-83 of coder relay CTP1 and bypassed at the back point of contact 82; (4) a driving circuit 84 for this coder relay which at times supplies the relay winding with pulsed pick-up current from code producing contacts 180b-75b over code selector contacts 90-89-85-86 of devices EVS-CD-DWI-DE and which at other times supplies the relay winding

with steady pick-up current from back contacts 87 and/or of 88 of devices HW and HE; (5) an energizing circuit 92 for transformer TTW which under all vacant section conditions supplies the transformer with coded current from source BX-CX over front contact 93 of coder relay CTP1 and which under occupied section conditions supplies the transformer with steady energy over front contact 94 of device EVS; and (6) a combined energizing and shunting circuit 95-98 for transformer TTE which normally bypasses the transformer primary through back contact 96 of device EVS but which at times supplies the transformer with "on" period pulses of coded current (from source BX-CX) over back contact 93 of devices CTP1 and EVS front contact 96 while establishing "off" period by-passes for the transformer primary at contact 97 of device CTP1.

The just described combination of track circuit apparatus for this east headblock section V-VI also is basically the same as that which the earlier identified Kemmerer application Serial No. 383,571 discloses and claims (see Kemmerer's Fig. 2); moreover, with the exception of being reversely arranged as to its normal energy supply end it substantially duplicates the corresponding combination for the earlier examined west headblock section I-II.

Like that west section I-II, this east headblock section V-VI is essentially a "detector" length of track. Under all vacant conditions thereof 180 code energy supplied to the west end transformer TTW over front coder contact 93 is transmitted by the section rails to the east end transformer TU (TTE now shorted at contact 96) and impressed upon relays TR1 and CD. Those relays are, in consequence, held picked up until a train enters one of the two section ends.

When such entry is at east location VI by a west-bound train, the supply of coded energy to west end transformer TTW continues but the driving circuit 84 for coder relay CTP1 becomes assigned, by contact 89 of the now released detector relay CD, to code selector contacts 87-85 of the traffic responsive relays HW-DW1 for westwardly extending section V-IV. In consequence, the west end of section VI-V now receives: (1) 180 code energy if at least two sections to the west of location V are vacant; (2) 75 code energy if only the first of these sections is vacant; and (3) steady energy (over back contact 87) if section V-IV is occupied. This energy, quite obviously, is suitable for controlling cab signals which the westbound train may carry.

When, at some other time, an eastbound train comes into section V-IV at the west end thereof: (1) the east-bound transformer TTE at once becomes conditioned to supply coded energy to the east end of the section; and (2) the driving circuit 84 for coder relay CTP1 becomes assigned to code selector contacts 88-86 of the traffic responsive relays HE-DE for the track to the east of location VI. These two actions are respectively effected by a picking up of contacts 96 and 90 of relay EVS.

That EVS pick-up, in turn, is produced by the train-effected release of relay CD's back contact 99 and it takes place over back contact 105 of device HW, front contact 108 of device HEP, and back contact 99 of device CD. Once effected it is prolonged by the completion at front contact 111 of relay EVS of a stick circuit which in-

cludes contacts 112 and 99 of devices NWP and CD.

As a result of the above stated actions, the east end of section V-VI now receives: (1) 180 code energy if at least two sections of track to the east are vacant; (2) 75 code energy if only the first of those sections is vacant; and (3) steady energy (over back contact 88) if the section adjoining location VI is occupied. By this energy cab signals carried by the eastbound train may, of course, be controlled in the usual manner.

Looking finally at the remaining equipment for the east headblock section V-VI, it will be seen: (1) that the repeater relay RWP for track switch W is picked up when and only when that switch connects the rails of passing track PS2 with those of the main track I-2; (2) that the companion relay NWP is picked up when and only when the siding rail connection just named is completely broken by the switch; (3) that the repeater relay CDP for detector device CD is governed solely by front contact 118 of that device and has slow pick-up characteristics; (4) that the "home" control relay HWM for signal SWM at proper times receives pick-up energy over front contact 139 of device HWP, front contact 120 of device CDP, front contact 121 of device NWP and back contact 122 of device HWS; (5) that the pick-up circuit for signal SWS's "home" control relay HWS includes front contacts 139 and 120 of devices HWP and CDP, front contact 123 of device RWP, and back contact 124 of device HWM; (6) that the pick-up circuit for signal SEV's "home" control relay HEP includes front contact 10 of device HE, and front contacts 140 and 127 of devices NWP and CDP; (7) that relay XVS receives pick-up current over back contact 76 of device CDP plus front contact 141 of devices HWP and either front contact 142 of device RWP or front contact 143 of device HWM plus back contact 144 of device HE and further is provided with a stick contact 145; (8) that the repeater relay VSP is controlled solely by contact 162 of device XVS; (9) that the "distant" control relay DW1 for signal SWM is governed solely by polar and neutral contacts 147 and 148 of relay ADW; and (10) that this neutral-polar relay ADW is provided with a line-wire control circuit 149-150 which extends westwardly to location IV (see Fig. 1d) where it terminates in contacts 151-152-153 of devices HW and HE.

The reason for this line-wire control circuit 149-150 will become evident from an analysis of "complete system" operation that later will be made with the aid of the Fig. 2 control limit diagram.

Track circuits for siding-spanning sections

Each length of main track I-2 that spans a passing siding PS2 has track circuit facilities which include: (1) at the siding east end the earlier described elements TTW, CTP, BX-CX and TRA that are shown at location I of Fig. 1a; and (2) at the siding west end the earlier described elements TTW, RC, BK-CK and TR that are shown at location VI of Fig. 1f. All elements in a typical siding spanning track circuit combination may, therefore, be examined by placing the diagram of Fig. 1f to the left of and in alignment with the diagram of Fig. 1a.

From such an examination the character of the illustrative siding spanning section VI-I will at once become apparent. As long as that sec-

tion remains vacant, "on" period pulses of "normal master" code energy supplied (from BX-CX through TTE) to the east end I thereof operate eastbound track relay TR at the west end VI and cause "off" period pulses of "feed back" energy to return to and operate westbound track relay TRA at east end I.

Entry of an eastbound train into the section west end VI cuts off all feed back energy transmission but does not alter the eastward traffic responsive operation of the master coder CTP at east end I. The "normal master" energy then supplied to that east end thus has: (1) the 180 code pattern if at least two sections to the east of I are vacant; (2) the 75 code pattern if only the first of those sections is vacant; and (3) the steady form if section I-II is occupied. By that normal master energy cab signals carried by the eastbound train may, of course, be controlled in conventional manner.

Entry, at some other time, of a westbound train into the section east end I drops track relay TR at west end VI and, by transferring (at contact 28) the RC relay driving circuit to transmitters 180-75CT, causes the section west end to be supplied with "special master" energy which has: (1) the 180 code pattern if at least two sections to the west of VI are vacant; (2) the 75 code pattern if only the first of these sections is vacant; and (3) the steady form if section VI-V is occupied. By that special master energy cab signals carried by the westbound train may, of course, be controlled in conventional manner.

Operation of the complete A. P. B. system

Description now having been given of the apparatus and circuits which the complete signaling system of Figs. 1a-1f utilizes, attention next will be directed to the manner in which that complete system operates to provide both wayside and cab signal indications of the special A. P. B. variety that the control limit diagram of Fig. 2 summarizes.

In the composite diagram of Figs. 1a-1f all wayside signals SE-SW and control devices therefor are shown in the condition that accompanies: (1) a complete absence of trains from the main line track stretch I-VI; (2) a placement of the west or PS1 track switch W in its normal or siding disconnected position; and (3) a placement of the east or PS2 track switch W also in its siding disconnected position. Under these conditions: (1) the eastbound main track signals SEM, SEIII, SEIV and SEV all are held at "clear"; (2) the eastbound siding leaving signal SES is held at "stop"; (3) the westbound siding leaving signal SWS also is held at "stop"; (4) the westbound headblock signal SWM is held at "clear"; (5) the westbound intermediate signals SWIV and SWIII are held at "approach"; and (6) the westbound siding entering signal SWII is held at "clear".

As has already been seen: (1) the just named "clear" showings by the several eastbound main track signals SE are produced by an east-to-west transmission of "normal master" 180 code energy through the rails of each of the system track sections; (2) the "stop" showing by location I's siding leaving signal SES results from the pick-up circuit for control relay HES being broken at contact 123 of the west switch repeater RWP; (3) the "stop" showing by location VI's westbound siding signal SWS results from control relay HWS's pick-up circuit being

broken at contact 123 of the east switch repeater RWP; (4) the "clear" showing by location VI's westbound headblock signal SWM results from "home" control relay HWM being energized over front contacts 121-126-139 of devices NWP-CDP-HWP and from "distant" control relay DW1 being held picked up through the medium of device ADW, line circuit 149-150 and devices HW-HE at location IV; (5) the "approach" showings by westbound intermediate signals SWIV and SWIII are produced by a west-to-east transmission of "feed back" energy pulses through the rails of track sections III-IV and II-III; and (6) the "clear" showing by westbound signal SWII results from "home" control relay HW1 being energized over front contacts 127-128 of devices CDP-HWP and from "distant" control relay DW being held picked up through the medium of line circuit 128-129 and device HWM at the west end (see Fig. 1e) of passing siding PS1.

Assume that an eastbound train now approaches the west headblock location I over the main track I-II. The "clear" showing by wayside signal SEM authorizes advancement into section I-II while the "normal master" 180 code energy fed toward the train from TTE at location I causes the train's cab signals also to show "clear."

Upon movement of the train's leading vehicle into section I-II, a "clear" indication is had from the advance wayside signal SEIII; 180 cab signal energy is received from location II's transformer TTE and westbound signal SWII goes to "stop." Also effected by the shunt-produced release of section I-II's devices TR1-CD-CDP is a breaking, at CDP's knockdown contact 30, of the driving circuit for section II-III's west bound coder relay RC.

This breaking continuously disconnects section II-III's west transformer TTW from the "feed back" (and/or "special master") source BK-CK and thereby continuously deenergises track relay TRA at the section east end III; that deenergization puts westbound signal SWIII at "stop," releases "knockdown" contact 30 of location III's relay HWP, and by removing all feed back energy from section III-IV continuously deenergized that section's track relay TRA at location IV; that deenergization puts westbound signal SWIV at "stop," releases the associated HWP, and by removing (again through "knockdown" contact 30) all west-to-east flowing energy from section IV-V drops track relay TRA at location V; and that dropping releases the associated devices HW-HWP and deenergizes, at contact 139, the "home" control relay HWM for the westbound headblock signal SWM at location VI.

By the latter action this location VI headblock device SWM is put at "stop" and the track section VI-Ia (see Fig. 2) to the east is conditioned for removal of all west-to-east flowing energy upon entry of a westbound train therein. That "stop" showing (and section conditioning), quite obviously, warns approaching westbound traffic that an eastbound train has entered the west end of the A. P. B. stretch, and it thus constitutes the before-mentioned directional protection for eastbound train moves. Once thus set up, moreover, this "stop" indication by device SWM is uninterruptedly continued as long as any part of the eastbound train remains in the stretch I-VI. That continuance results, as will be seen, from the fact that each advance of the train into a succeeding track section to the east does not dis-

turb the previously effected deenergized condition for the westbound track circuit of that succeeding section.

In conformity with the control limits which Fig. 2 represents, the just described westbound track circuit "knockdown" is terminated at location VI and it does not continue therebeyond even though the HWP contact 160 at location V has released. Preceding that release: (1) device HW at location IV dropped its contacts 151-152 and thereby reversed the polarity of the energy applied to line circuit 149-150; (2) relay ADW at location V responded to that reversal by shifting its polar contacts 147-158-136 to the right; and (3) as so shifted contact 158 set up a bypass circuit for "knockdown" contact 160.

In consequence the supply at location VI of "feed back" energy to the PS2 spanned section to the east continues until such time as a westbound train comes into that east section and releases relay HE therefor. Upon such a release HE's contact 45 removes all west-to-east flowing energy from the section rails and thereby produces a "stop" showing on the part of cab signals which the westbound train may be carrying.

Under this and the earlier described eastbound directional protection which the westbound signals SWII-SWIII-SWIV-SWM provide, the eastbound train now is free to move on into and through track stretch I-VI. As the train advances into section II-III, it continues to get "clear" from advance wayside signal SEIII and also receives 180 cab signal code energy from location III's transformer TTE; as the train moves on into section III-IV it gets the "clear" indication from eastbound wayside signal SEIV and receives 180 cab signal energy from location IV's transformer TTE; as the train further advances into section IV-V it gets "clear" from signal SEV and receives 180 cab signal energy from location V's transformer TTE; as the train moves on into section V-VI it gets the "clear" indication from the eastbound wayside signal SEMa (see Fig. 2) at the east end of siding PS2 and receives 180 cab signal energy from location VI's transformer TTE; and as the train further advances into section VI-Ia (again see Fig. 2) it continues to get "clear" from wayside signal SEMa (Fig. 2) and receives 180 cab signal energy from location Ia's (see Fig. 1a) transformer TTE.

In thus progressing through the stretch each eastbound train also sets up its own following protection. Such following protection set-up is effected automatically through the medium of the earlier described "eastbound" or "normal master" code track circuit facilities and the signal indications incident thereto are displayed not only along the right of way by the wayside devices SE but also on board each following train that is provided with cab signal apparatus of conventional "frequency code" character.

As, for example, the before named eastbound train enters the A. P. B. stretch I-VI from the west and advances past locations I, III, IV and V thereof, it successively deenergizes the track relays TR at those locations and thus successively conditions: (1) each of the wayside signals SEM, SEIII, SEIV and SEV to show "stop"; and (2) each associated track transformer TTE to supply the rails of the section to the west with "normal master" energy of the 75 code (or other restrictive) form.

Once established, moreover, the resulting "stop" aspect showing by each eastbound signal persists until the trailing vehicle of the train

clears the next location to the east. When that happens: (1) the rails of the just vacated section transmit this normal master 75 energy to the track relay TR at the west end thereof; (2) the wayside signal SE at that west end is thereby conditioned to show "approach"; and (3) the track transformer TTE at the same location is connected to supply the rails of the succeeding section to the west with energy of the "normal master" 180 code. At the west end of that succeeding section the track relay TR responds in the usual manner and: (1) conditions the wayside signal SE which it controls to display "clear"; and (2) causes the track transformer TTE to supply normal master 180 code energy to the rails of the succeeding section to the west.

The inclusion of the west headblock section I-II in the track and signal layout of Figs. 1a-1f modifies the just stated following protection actions to the extent brought out below. While the before named eastbound train occupies section I-II, it puts (by dropping location I's device TR1-CD-CDP and deenergizing relay HEM at contact 120) the eastbound headblock signal SEM at "stop" but removes (by breaking CTP's driving circuit 13 at CDP's contact 17) all "normal master" energy from the west section I-aVI (see Fig. 2) which siding PS1 spans; while just beyond location II the train continues (by keeping HEM deenergized at HE's contact 10) signal SEM at "stop" and supplies (over CDP's front contact 17 and HEM's back contact 71) "normal master" 75 code energy to section I-aIV; while just beyond location III the train allows (by permitting "normal master" 75 code energy from location III to reach location II and there pick up relays HE-HES) location I's signal SEM to go to "approach" and changes (at HEM's front contact 71) the "normal master" energy for section I-aVI from the 75 to the 180 code pattern; and when just beyond location IV the train allows (by shifting section II-III's "normal master" energy to the 180 code and thereby picking up location II's relay DE) location I's signal SEM to go to "clear."

In the intermediate track sections II-III, III-IV and IV-V the eastbound following protection actions are essentially as earlier summarized. Contributing thereto, however, is the east bound stick relay ES at each of locations III and IV. From before the train enters the west end of the section to the east of each relay ES until it clears the east end of that section, contact 19 of the relay is picked up. That pick-up, in turn, continues intact the driving circuit 13 (otherwise broken at HEP's contact 17) for the westwardly extending section's master coder relay CTP and thereby assures the proper supply of following protection energy to that section.

In the east headblock section V-VI this eastbound directional protection involves certain special features now to be examined. When the before named eastbound train occupies section V-VI it puts (by dropping location VI's devices TR1-CD-CDP and deenergizing relay HEP at contact 127) the eastbound signal SEV at "stop" but removes (by breaking CTP's driving circuit at CDP's contact 17) all "normal master" energy from the west section V-IV; when just beyond location VI the train continues (by keeping HEP deenergized at HE's contact 10) signal SEV at "stop" and supplies (over CDP's front contact 17 and HEP's back contact 56) "normal master" 75 code energy to section V-IV; when

just beyond location IIa (see Fig. 2 and also Figs. 1a-1b) at the east of siding PS2 the train allows (by permitting "normal master" 75 code energy from location Ia to reach location VI and there pick up relays HE-HEP) signal SEV to go to "approach", and continues (at front and back contacts 56 and 71 of devices HEP-DE) the supply of "normal master" 75 energy to section V-IV; and when just beyond location IIIa (see Figs. 1a-1b-1c) the train allows (by shifting section VI-Ia's "normal master" energy to the 180 code and thereby picking up relay DE) the eastbound signal SEV to go to "clear."

The just traced eastbound train movement through the A. P. B. stretch of Figs. 1a-1f involved an entry thereinto which was by way of the main line track to the immediate west of location I. Eastbound train entry by way of the siding track PS1 also is at times made and in that situation the actions earlier described are modified to the extent noted below.

To set up such an eastbound entry from the west passing siding PS1, the east track switch W therefor (see Figs. 1a-1b) must, of course, first be shifted (either manually or by means of remote control mechanism not shown) to its reversed position wherein the siding rails are connected with those of the main track I-2. This shift picks up repeater relay RWP and releases the companion device NWP.

By those actions: (1) contact 121 deenergizes "home" control relay HEM and thereby holds the main track eastbound signal SEM at "stop"; and (2) contact 123 completes the pick-up circuit for "home" control relay HES and thereby causes the siding leaving signal SES to show one of its permissive indications. That indication is selected by location II's relay DE and will be: (1) "clear" if sections II-III and III-IV are both vacant; and (2) "approach" if only section II-III is vacant.

Under the authority of this indication the eastbound train is free to move from siding PS1 over the switch W and thence into the main track section I-II. From that point the actions are as earlier described.

Instead of leaving the A. P. B. stretch by way of the main track I-2 to the east of location VI, the eastbound train may at times be diverted to the east passing siding PS2. In that situation the actions earlier described are modified to the extent noted below.

To set up such an eastbound train routing to siding PS2, the west track switch W therefor (see Figs. 1e-1f) must, of course, first be shifted (either manually or by means of remote control mechanism not shown) to its reversed position wherein the siding rails are connected with those of the main track I-2. This shift picks up repeater relay RWP and releases the companion device NWP.

Under these conditions: (1) contact 121 of relay NWP continues the "home" control relay HWM deenergized and thereby holds the main track westbound signal SWM at "stop"; (2) the eastbound train shunt of section IV-V keeps HWP's contact 139 released and by there breaking relay HWS's energizing circuit retains the siding leaving signal SWS at "stop"; and (3) contact 140 of relay NWP breaks relay HEP's energizing circuit and thereby puts the siding entering signal SEV at "stop." Under the authority of rules and its own train orders, the eastbound train now is permitted to run past this

"stop" showing device SEV and into the siding track PS2.

The directional and following protection actions which accompany eastbound train moves 5 through the A. P. B. stretch of Figs. 1a-1f now having been examined, attention will next be directed to the corresponding actions which accompany the passage of westbound trains through the stretch.

To start this westbound explanation it will again be assumed that all wayside signals SE-SW and control devices therefor have the condition (shown by Fig. 1) which accompanies: (1) a complete absence of trains from the main line track stretch I-VI; (2) a placement of the west or PS1 track switch W in its normal position; and (3) a placement of the east or PS2 track switch W also in its normal position. Under these conditions it has been seen: (1) that the east bound main track signals SE all are held at "clear"; (2) that the eastbound siding leaving signal SES is held at "stop"; (3) that the westbound siding leaving signal SWS also is held at "stop"; (4) that the westbound headblock signal SWM is held at "clear"; (5) that the westbound intermediate signals SWIV and SWIII are held at "approach"; and (6) that the westbound siding entering signal SWII is held at "clear."

Assume that a westbound train now approaches the east headblock location VI over the main track I-2 and causes (see the control limit diagram of Fig. 2) eastbound signal SEV to display "stop." The "clear" showing by wayside signal SWM authorizes advancement into section VI-V while "special master" 180 code energy fed toward the train from TTW at location VI causes the train's cab signals also to show "clear."

This "special master" energy supply began 40 when the train first shunted the rails of section VI-Ia (see Figs. 1 and 1a); it resulted from the release of location VI's track relay TR and the accompanying assignment at HE's contact 28 of the RC relay driving circuit 36 to the headblock code transmitters 180-75CT; and it replaced the "off" period pulses of "feed back" energy (which during vacant section conditions were supplied under the control of the then operating relay TR) with "special master" pulses that are distinctively coded in accordance with traffic conditions to the west.

Upon movement of the train's leading vehicle into section VI-V, 180 cab signal code energy is received from location V's transformer TTW; 55 eastbound signal SEV remains at "stop"; and the advance westbound signal SWIV shifts its indication from "approach" to "clear." That shift is initiated by the shunt-produced release of section VI-V's devices TR1-CD-CDP and the resultant breaking, at CDP's "knockdown" contacts 17, of the driving circuit for section V-VI's eastbound coder relay CTP.

This breaking continuously disconnects section V-IV's east transformer TTE from the "special master" source BX-CX and thereby continuously deenergizes track relay TR at the section west end IV; that deenergization puts eastbound signal SEIV at "stop"; releases "knockdown" contact 17 of location IV's relay HEP, and by removing all "normal master" energy from section V-III continuously deenergizes that section's track relay TR at location III; that deenergization puts eastbound signal SEIII at "stop" through a release of the associated HEP, and by removing (again through "knockdown" contact

17) all east-to-west flowing energy from section III-II drops track relay TR at location II; and that dropping releases the associated device HE and deenergizes, at contact 10, the "home" control relay HEM for the eastbound headblock signal SEM at location I.

By the latter action this location I headblock device SEM is put at "stop" and the track section I-VI (see Fig. 2) to the east is conditioned for removal of all east-to-west flowing energy. That "stop" showing (and section conditioning), quite obviously, warns approaching eastbound traffic that a westbound train has entered the east end of the A. P. B. stretch and it thus constitutes the before mentioned directional protection for westbound train moves. Once thus set up, moreover, this "stop" indication by device SEM is uninterrupted continued as long as any part of the westbound train remains in the stretch VI-I. That continuance results, as will be seen, from the fact that each advance of the train into a succeeding track section to the east does not disturb the previously effected deenergized condition for the eastbound track circuit of that succeeding section.

In conformity with the control limits which Fig. 2 represents, the just described eastbound track circuit "knockdown" is terminated at location I and it does not continue therebeyond even though the HEM contact 17 at location II has released.

A further result of the westbound train entry into section VI-V is a "presetting" of all advance westbound track circuits in the stretch. By this presetting the "off" period pulses of "feed back" section energy (from west source BK-CK) are replaced by "special master" code energy, earlier described as consisting of recurring pulses that are distinctively modulated in accordance with traffic conditions to the west and that are suitable for controlling both wayside signals and train carried cab signals.

First to be so "preset" by the shunt of section VI-V is section V-IV. By the earlier explained "knockdown" of the eastbound track circuit therefor, relays TR-HE at west end IV were dropped; that dropping caused HE's contact 28 to transfer RC's driving circuit 36 to location IV's code transmitter 180CT; and that transfer replaced the section's "feed back" pulses with "special master" energy of the 180 code pattern. Next, similar presetting actions were effected by section IV-III; and these were followed by a corresponding "special master" code conditioning on the part of section III-II.

By the "special master" energy of the so preset track sections IV-III and III-II, the westbound intermediate signals SWIV and SWIII are both put at "clear." Such indication selection results from the fact that the controlling track relay TRA receives and follows the sections "special master" 180 code energy and not only picks up "home" relay HW but also the "distant" relay DW, over back contact 37 of the now released eastbound repeater HEP.

Under the earlier described directional protection which the eastbound signals SEV-SEIV-SEIII-SEM provide, the westbound train now is free to move on into and through track stretch VI-I. As the train advances into section V-IV it continues to get "clear" from the advance wayside signal SWIV and also receives 180 cab signal code energy from location IV's transformer TTW; as the train moves on into section IV-III it gets the "clear" indication from westbound wayside

signal SWIII and receives 180 cab signal energy from location III's transformer TTW; as the train further advances into section III-II it gets "clear" from signal SWII and receives 180 cab signal energy from location II's transformer TTW; as the train moves on into section II-I it gets the "clear" indication from the westbound wayside signal SWMa (see Fig. 2) at the west end of passing siding PS1 and receives 180 cab signal energy from location I's transformer TTW; and as the train further advances into section I-VIa (again see Fig. 2) it continues to get "clear" from wayside signal SWMa (Fig. 2) and receives 180 cab signal energy from location VIa's (see Fig. 1f) transformer TTW.

In thus progressing through the stretch each westbound train also sets up its own following protection. Such following protection set-up is effected automatically through the medium of the earlier described "westbound" ("special master" code BK-CK energy) track circuit facilities and the signal indications incident thereto are displayed not only along the right of way by the wayside devices SW but also on board each 25 following train that carries cab signal apparatus.

As, for example, the before named westbound train enters the A. P. B. stretch from the east and advances past locations VI, IV, III and II thereof, it successively deenergizes the track relays TRA at those locations and thus successively conditions: (1) each of the wayside signals SWM, SWIV, SWIII and SWII to show "stop"; and (2) each associated track transformer TTW to supply the rails of the section to the east with "special master" energy of the 15 code (or other restrictive) form.

Once established, moreover, the resulting "stop" aspect showing by each westbound signal persists until the trailing vehicle of the train 40 clears the next location to the west. When that happens the just vacated section goes through the earlier described "reset" operations by which its "special master" code energy becomes replaced by "feed back" pulses that coincide with the "off" periods of the "normal master" code energy which then is received from the east.

Should, however, a second train be following the first through the A. P. B. stretch, this track circuit reset does not take place. Instead: (1) 50 the rails of the section just vacated by the first train transmit "special master" 15 code energy to the track relay TRA at the east end of that section; (2) the wayside signal SW at that east end is thereby conditioned to show "approach"; and (3) the track transformer TTW at the same 55 location is connected to supply the rails of the succeeding section to the east with energy of the "special master" 180 code.

The inclusion of the east headblock section 60 VI-V in the track and signal layout of Figs. 1a-f modifies the just stated following protection actions to the extent brought out below. While the before named westbound train occupies section VI-V it puts (by dropping location VI's devices TR1-CD-CDP and deenergizing relay HWM at contact 120) the westbound headblock signal SWM at "stop" but removes (by breaking RC's driving circuit 36 at CDP's contact 156) all westbound control energy from the east 65 section VI-Ia (see Fig. 2) which siding PS2 spans; while just beyond location V the train continues (by keeping HWM deenergized at HWP's contact 139) signal SWM at "stop" and supplies (over contacts 20 and 28 of devices HWM and HE) "special master" 15 code to section 70 75

VI—Ia; while just beyond location IV the train allows (by causing devices HEP—HWP at IV to reverse the polarity of line circuit 149—150 and deenergize "distant" relay DW1 at ADW's contact 147) location IV's signal SWM to go to "approach" and changes (at HWM's front contact 20) the "special master" energy (for a following train) for section VI—Ia from the 75 to the 180 code pattern; and when just beyond location III the train allows (by permitting devices HWP—HEP at IV to restore normal polarity to line circuit 149—150 and thereby pick up "distant" relay DW1) location VI's signal SWM to go to "clear."

In the intermediate track sections V—IV, IV—III and III—II the westbound following protection actions are essentially as earlier summarized. Contributing thereto, however, is the westbound stick relay WS at each of locations IV and III. From before the train enters the east end of the section to the west of each relay WS, until it clears the west end of that section, contact 29 of the relay is picked up. That pick-up, in turn, continues intact the driving circuit 36 (otherwise broken at HWP's contact 30) for the 25 eastwardly extending section's special coder relay RC and thereby assures the proper supply of following protection energy to that section.

In the west headblock section II—I this westbound directional protection involves certain special features now to be explained. When the before named westbound train occupies section II—I it puts (by dropping location I's devices TR1—CD—CDP and deenergizing relay HW1 at contact 121) the westbound signal SWII at "stop" but removes (by breaking RC's driving circuit 36 at CDP's contact 30) all "special master" energy from the east section II—III; when just beyond location I the train continues (by keeping HW1 deenergized at HWP's contact 126) signal SWII at "stop" and supplies (over HW1's back contact 18, HE's back contact 28 and CDP's front contact 30) section II—III with "special master" 35 75 code energy which effects (by the aid of devices SCP—CCR in the manner earlier explained) "reset" of the sections track circuit and thereby puts signal SWIII at "approach"; when just beyond location VIA (see Fig. 2 and also Fig. 1f) at the west end of passing siding PS1, the train retains (by keeping RC's driving circuit 36 open at CDP's contact 156) signal SWII at "stop"; when just beyond location Va (see Fig. 2 and also Fig. 1e) still further to the west the train allows (by releasing HWM—see Fig. 1e—and deenergizing the line supply circuit for "distant" relay DW) signal SWII to go to "approach" and continues (at contacts 18—28—30 of devices HW1—HE—CDP) the supply of "feed back" energy to section II—III; and when just beyond location IVa (see Fig. 1d) the train allows (by causing device HWM at Va to reenergize line circuit 128—129 and pick up DW at I) the westbound signal SWII to go to "clear."

The just traced westbound train movement through the A. P. B. stretch of Figs. 1a—1f involved an entry thereinto which was by way of the main line track to the immediate east of location VI. Westbound train entry by way of the siding track PS2 also is at times made and in that situation the actions earlier described are 70 modified to the extent noted below.

To set up such a westbound entry from the east passing siding PS2, the west track switch W therefor must, of course, first be shifted (either manually or by means of remote control mecha-

nism not shown) to its reversed position wherein the siding rails are connected with those of the main track I—2. This shift picks up relay RWP and releases the companion device NWP.

5 By those actions: (1) contact 121 deenergizes "home" control relay HWM and thereby holds the main track westbound signal SWM at "stop"; and (2) contact 123 completes the pick-up circuit for "home" control relay HWS and thereby causes the siding leaving signal SWS to show one of its permissive indications. That indication is selected by location V's relay DW1 and will be: (1) "clear" if sections V—IV and IV—III are both vacant; and (2) "approach" if only section V—IV is vacant.

Under the authority of this indication the westbound train is free to move from siding PS2 over the switch W and thence into the main track section VI—V. From that point the actions are as earlier described.

20 Instead of leaving the A. P. B. stretch by way of the main track I—2 to the west of location I, the eastbound train may at times be diverted to the west passing siding PS1. In that situation the actions earlier described are modified to the extent noted below.

To set up such a westbound train routing to siding PS1, the east track switch W therefor (see Figs. 1a—1b) must, of course, first be shifted to its reversed position wherein the siding rails are connected with those of the main track I—2. This shift picks up repeater relay RWP and releases the companion device NWP.

Under these conditions: (1) contact 121 of 35 relay NWP continues the "home" control relay HEM deenergized and thereby holds the main track eastbound signal SEM at "stop"; (2) the westbound train shunt of section III—II keeps HE's contact 10 released and by there breaking relay HES's energizing circuit retains the siding leaving signal SES at "stop"; and (3) contact 113 of relay NWP breaks relay HW1's energizing circuit and thereby puts the siding entering signal SWII at "stop." Under the authority of 40 rules and its own train orders, the westbound train now is permitted to run past this "stop" showing device SWII and into the siding track PS1.

45 It is believed that the representative train moves just traced will serve: (1) to show how the complete A. P. B. system of Figs. 1a—1f operates; and (2) to bring out the function that is performed by each and every device in the system. The device functionings under such further traffic condition combinations as may not have specifically been described will, it is thought, become evident from an examination of the control limit diagram of Fig. 2 and a review of the apparatus description already given.

Cut location apparatus of Fig. 3

50 All of the description so far given has assumed that the rails of each of the main signal blocks (II—III, III—IV, IV—V, etc.) of track in the A. P. B. system are electrically continuous and thus constitute the conductors of but a single track section. In the composite diagram of Fig. 1 such a condition is in fact shown for each and every one of the sections illustrated.

55 Our improved coded track circuit system of A. P. B. signaling is, however, not restricted to applications of this type alone but may also be applied to stretches of track wherein one or more of the main signal blocks is, because of excessive length or other reasons, divided into two or more

track circuit sections. In such situations we propose to equip each point of signal block subdivision with cut section facilities of the type represented in Fig. 3.

There a subdividing location, designated by the character IIIx, is shown as being produced by interposing insulated rail joints 3 between the west and the east ends of the earlier named signal block III-IV of Figs. 1c-d. Obviously, of course, the same facilities may be used in a comparable manner in any of the remaining signal blocks of the A. P. B. system.

When so installed, the cut section facilities of Fig. 3 perform functions which are comparable to those performed by the equipment at each of the intermediate signal locations III and IV of Figs. 1c and 1d. At the cut location IIIx, however, these functions differ in that no wayside signals are there controlled and also in that no trackway codes are there independently generated.

Comprised by these cut location facilities of Fig. 3 are: (1) track circuit elements TTW, RC, BK-CK and TR which correspond to the similarly identified elements at each of the intermediate locations III and IV; (2) other track circuit elements TTE, CTP, BX-CX and TRA which also correspond to the similarly identified devices at the intermediate locations; and (3) decoding devices DT and H which likewise function in the same manner as at the intermediate locations.

These elements and devices at location IIIx function: (1) to repeat all eastbound control pulses of "normal master" code energy received from the east around the cut joints 3 and into the rails to the west; (2) to repeat steady "normal master" energy from the east into the rails to the west; (3) to supply the east rails with "off" period pulses of "feed back" energy whenever master code energy is being received from those rails; and (4) to repeat westbound control pulses of "special master" code energy received from the west around the cut and into the rails to the east.

The functions of "normal master" energy repeating are performed by the eastbound track relay TR through the medium of contacts 164 and 165. These contacts respectively form parts of the control and supply circuits 13 and 43 for the eastbound transformer TTE. By them energy received by relay TR from the rails to the east of location IIIx is directly repeated into the rails to the west of that location.

If this east received energy be in the form of recurring code pulses, the west repeated energy will have precisely the same pulsed form; if the east received energy be steady or uninterrupted, the west repeated energy will have that same steady form; if the east energy reception be entirely cut off, the west rails also will be deenergized; and upon resumption of that east energy reception, the west rails will have impressed thereon an initial pulse of BX-CX energy which is prolonged to in excess of 0.4 second and which aids track circuit reset.

This prolonged pulse results from the joint action of contacts 166-167-168 of devices HE-HEP. With devices TR-HE-HEP all released, the west energy control and supply circuits 13 and 43 are respectively broken at contacts 163 and 168. Upon the first pulse of east received energy relays TR and HE quickly pick up, and relay HEP follows after an interval of about 0.4 second. During this interval, coder

CTP is held continuously picked up over front contact 166 and back contact 167 and transformer TTE is continuously energized over back contact 168.

5 The resulting energy with which the west rails are initially supplied thus has the same "single code pulse" form as at times is produced by the auxiliary relay SCP at signal locations III and IV. It effects reset aiding actions which are identical to those earlier examined in connection with relays SCP.

10 The cut location functions of "feed back" energy supply and "special master" energy repeating are performed by the westbound track relay 15 TRA through the medium of contacts 34-80 and by the aid of contacts 170-171 of device HW.

15 When picked up, as shown, contacts 28-170 of HE-HW connect the westbound coder relay RC with impulse transformer 27 and thereby cause 20 the east rails to be supplied with "off" period pulses of "feed back" energy, under the control of the now operating track relay TR.

25 When those east rails are shunted and the west rails are unshunted, HE's contact 28 transfers the RC driving circuit 36 (includes front contact 170) to contact 34 of westbound track relay TRA. "Special master" westbound control energy received from the west is by TRA contacts 34 and 80 now repeated into the east rails over 30 HE's back contact 45.

35 From the foregoing it will therefore be apparent that the cut section facilities of Fig. 3 may be interposed within the limits of any one of the signal block track lengths which the coded A. P. B. system of Fig. 1 embraces without in any way interfering with the operation of that system.

Summary

40 While the improvements of our invention have been disclosed in connection with an A. P. B. system (Figs. 1a-1f) which includes only two intermediate signal locations (III and IV) and which provides for only three indications ("clear," "approach" and "stop") on the part of the controlled signals, it will be apparent that 45 these same improvements also may be applied to systems: (1) wherein the single track stretch includes either more or less than two intermediate locations; and/or (2) wherein the signals identified with the stretch are controlled to either 50 more or less than three indications.

55 By the aid of these improvements we have provided a completely automatic A. P. B. system of coded track circuit signaling: (1) which gives both wayside and cab indications; (2) which incorporates numerous apparatus organizations of new and superior form; (3) which utilizes track circuit reset facilities of novel and highly effective character; and (4) which provides features of reliability and safety not heretofore attainable.

60 Although we have herein shown and described only one form of A. P. B. signaling apparatus embodying our invention, it is understood that various changes and modifications may be made therein within the scope of the appended claims without departing from the spirit and scope of our invention.

Having thus described our invention, what we 65 claim is:

1. Apparatus for use at an intermediate location in an absolute permissive block railway signal system, said location being defined by the adjacent ends of two adjoining track sections each supplied at their respective remote ends

with track circuit energy coded at one or another of a plurality of code rates, comprising the combination with two code following track relays one for each section receiving energy respectively from the rails of the associated section at the end adjacent the other of said sections, two decoding relays one for each track relay, means controlled by each track relay for energizing its associated decoding relay in response to coded energy received from the rails of its associated section, two repeater relays one for each decoding relay, two directional stick relays one for each repeater relay, an energizing circuit for each repeater relay comprising a front contact of its associated decoding relay and a back contact of the other stick relay, a pick-up circuit for each stick relay comprising a back contact of the other stick relay and a back contact of the other repeater relay and a front contact of its associated repeater relay, a stick circuit for each stick relay comprising its own front contact and a back contact of the associated decoding relay, and means for governing traffic on said stretch and controlled by said two repeater relays.

2. The apparatus of claim 1 further characterized by the provision of means controlled by one of said stick relays for at times providing a snubbing or short-circuit path across the terminals of its associated repeater relay for at times altering the release period of such repeater relay.

3. The apparatus of claim 1 further characterized by the provision of a snubbing resistor across the terminals of one of said repeater relays for adjusting the release period of such relay, and means controlled by the associated decoding relay for at times providing a shunt or short-circuit path around said resistor.

4. The apparatus of claim 1 further characterized by the provision of a snubbing resistor across the terminals of one of said repeater relays for adjusting the release period of such relay, means controlled by its associated decoding relay for at times providing a shunt path around said resistor, and other means controlled by its associated stick relay for at times connecting in multiple with said resistor another resistor for altering the adjusted release period of said relay.

5. Apparatus for use at an intermediate location in an absolute permissive block railway signal system, said location being defined by the adjacent ends of two adjoining track sections each supplied at their respective remote ends with track circuit energy coded at one or another of a plurality of code rates, comprising the combination with two code following track relays one for each section receiving energy respectively from the rails of the associated section at the end adjacent the other of said sections, two decoding relays one for each track relay, means controlled by each track relay for energizing its associated decoding relay in response to coded energy received from the rails of its associated section, two repeater relays one for each decoding relay, two directional stick relays one for each repeater relay, an energizing circuit for each repeater relay comprising a front contact of its associated decoding relay and a back contact of the other stick relay, a pick-up circuit for each stick relay comprising a back contact of the other stick relay and a front contact of its associated repeater relay, a stick circuit for each stick relay comprising its own front contact and a back contact of its associated decoding relay, code generating means controlled by said two repeater relays for normally supplying to one of said two sections track circuit energy coded at a rate corresponding to the rate of operation of the track relay of such section, a track circuit source, means controlled by said two repeater relays for normally coupling said source to the

circuit for each stick relay comprising its own front contact and a back contact of the associated decoding relay, a signal governing traffic in one direction in one of the adjoining two sections and controlled by the repeater relay associated with the track relay of the said one section, and another signal governing traffic in the opposite direction in the other of said two adjoining sections and controlled by the other of said two repeater relays.

6. Apparatus for use at an intermediate location in an absolute permissive block railway signal system, said location being defined by the adjacent ends of two adjoining track sections each supplied at their respective remote ends with track circuit energy coded at one or another of a plurality of code rates, comprising the combination with two code following track relays one for each section receiving energy respectively from the rails of the associated section at the end adjacent the other of said sections, two decoding relays one for each track relay, means controlled by each track relay for energizing its associated decoding relay in response to coded energy received from the rails of its associated section, two repeater relays one for each decoding relay, two directional stick relays one for each repeater relay, an energizing circuit for each repeater relay comprising a front contact of its associated decoding relay and a back contact of the other stick relay, a pick-up circuit for each stick relay comprising a back contact of the other stick relay and a back contact of the other repeater relay and a front contact of its associated repeater relay, a stick circuit for each stick relay comprising its own front contact and a back contact of the associated decoding relay, means controlled by the repeater relay associated with one of the track relays for one of the adjoining two sections for normally supplying coded track circuit energy to the other of said two sections, and means rendered effective when said one repeater relay and its associated decoding relay is released and the other repeater relay is energized for supplying coded track circuit energy to the said one section.

7. Apparatus for use at an intermediate location in an absolute permissive block railway signal system, said location being defined by the adjacent ends of two adjoining track sections, comprising a track relay at the adjacent end of one of said two sections and another track relay at the adjacent end of the other of said two sections, two decoding relays one for each track relay and each controlled by its associated track relay to detect a code operation of such relay, two slow acting repeater relays one for each decoding relay, two directional stick relays one for each decoding relay, an energizing circuit for each repeater relay comprising a front contact of its associated decoding relay and a back contact of the other stick relay, a pick-up circuit for each stick relay comprising a back contact of the other stick relay and a front contact of its associated repeater relay, a stick circuit for each stick relay comprising its own front contact and a back contact of its associated decoding relay, code generating means controlled by said two repeater relays for normally supplying to one of said two sections track circuit energy coded at a rate corresponding to the rate of operation of the track relay of such section, a track circuit source, means controlled by said two repeater relays for normally coupling said source to the

other of said sections, means for coding the energy supplied from said source, and means controlled by the decoding relay associated with the said one track section for at times rendering said code generating means ineffective and for coupling said source to the said one track section.

8. In combination with a stretch of railway track divided into a plurality of successive adjoining track sections, each of said sections having at one end thereof a source of trackway energy and a first code following track relay and coding means constantly operating contacts to repeatedly connect the rails of the associated section first to said source and then to the winding of the said first track relay for producing coded track circuit energy consisting of alternate "on" and "off" intervals the latter of which coincide with said relay winding connections, each of said sections having at the opposite end thereof another code following track relay connected with the rails and having code generating means for supplying energy to the rails of its associated section during each "off" interval of the coded track circuit current therein, means controlled by the first-mentioned track relay and the other track relay at the adjacent ends of two adjoining track sections for controlling the code generating means associated with the said other track relay to render such means inactive and to supply the rails of the associated section with energy coded by the coding means at such location, and means controlled by each first track relay and by each other track relay for governing traffic on said stretch.

9. Apparatus for use at an intermediate location in an absolute permissive block railway signal system, said location being defined by the adjacent ends of two adjoining track sections, each of said sections having at one end thereof a source of trackway energy and a code following track relay and coding means operating contacts to repeatedly connect the rails of the associated section first to said source and then to the winding of the said track relay for producing in such section coded track circuit energy consisting of alternate "on" and "off" intervals the latter of which coincide with said relay winding connections, each of said track sections having at the opposite end thereof another code following track relay and code repeating means having contacts normally connecting the rails of the associated section to the winding of the said other track relay and which contacts when operated disconnect such relay from the rails and connect to such rails a source of energy, each of said sections having two decoding relays one for the first-mentioned and the other for the other track relay of the associated section and each decoding relay controlled by its associated track relay to detect a code operation of such relay, two slow acting repeater relays at said intermediate location, a first repeater relay for the decoding relay of the first track relay associated with the adjacent end of one of the two adjoining track sections and a second repeater relay for the decoding relay of the other track relay associated with the adjacent end of the other of the two adjoining track sections, two stick relays at said intermediate location, one stick relay for each repeater relay, an energizing circuit for each repeater relay comprising a front contact of its associated decoding relay and a back contact of the other stick relay, a pick-up circuit for each stick relay comprising a back contact of the other stick relay and a back contact of the other repeater relay and a front contact of its associated repeater relay, a stick circuit for each stick relay comprising its own front contact and a back contact of the associated decoding relay, code generating means associated with each of said other track relays and normally responsive to the operation of the associated relay for operating its associated code repeating means at a rate corresponding to the rate of operation of

other stick relay and a back contact of the other repeater relay and a front contact of its associated repeater relay, a stick circuit for each stick relay comprising its own front contact and a back contact of the associated decoding relay, circuit means controlled by said repeater relays at said intermediate location for normally operating the code repeating means at such location in response to each release of the associated other track relay at such location, and means also controlled by said repeater relays for at times causing operation of the associated code repeating means in response to operation of the coding means at such location.

10. The apparatus of claim 9 further characterized by the provision of means at said intermediate location for providing the first track relay at such location with a stick circuit comprising a source of energy and a contact of the associated coding means and having two alternate paths one including a front contact of the repeater relay for the other track relay at such location and the other path including a front contact of the stick relay associated with the said repeater relay of the said other track relay.

11. Apparatus for use at an intermediate location in an absolute permissive block railway signal system, said location being defined by the adjacent ends of two adjoining track sections, each of said sections having at one end thereof a source of trackway energy and a code following track relay and coding means operating contacts to repeatedly connect the rails of the associated section first to said source and then to the winding of the said track relay for producing in such section coded track circuit energy consisting of alternate "on" and "off" intervals the latter of which coincide with said relay winding connections, each of said track sections having at the opposite end thereof another code following track relay and code repeating means having contacts normally connecting the rails of the associated section to the winding of the said other track relay and which contacts when operated disconnect such relay from the rails and connect to such rails a source of energy, each of said sections having two decoding relays one for the first-mentioned and the other for the other track relay of the associated section and each decoding relay controlled by its associated track relay to detect a code operation of such relay, two slow acting repeater relays at said intermediate location, a first repeater relay for the decoding relay of the first track relay associated with the adjacent end of one of the two adjoining track sections and a second repeater relay for the decoding relay of the other track relay associated with the adjacent end of the other of the two adjoining track sections, two stick relays at said intermediate location, one stick relay for each repeater relay, an energizing circuit for each repeater relay comprising a front contact of its associated decoding relay and a back contact of the other stick relay, a pick-up circuit for each stick relay comprising a back contact of the other stick relay and a back contact of the other repeater relay and a front contact of its associated repeater relay, a stick circuit for each stick relay comprising its own front contact and a back contact of the associated decoding relay, code generating means associated with each of said other track relays and normally responsive to the operation of the associated relay for operating its associated code repeating means at a rate corresponding to the rate of operation of

the said associated relay, means controlled by the repeater relay of the first track relay associated with one of two adjacent sections for rendering ineffective the code generating means of the other of said two adjoining sections, and means controlled by the repeater relay of the other track relay of the said other section for controlling the code rate at which said coding means codes said track circuit energy supplied to the said one section.

12. Apparatus for use at an intermediate location in an absolute permissive block railway signal system, said location being defined by the adjacent ends of two adjoining track sections, each of said sections having at one end thereof a source of trackway energy and a code following track relay and coding means operating contacts to repeatedly connect the rails of the associated section first to said source and then to the winding of the said track relay for producing in such section coded track circuit energy consisting of alternate "on" and "off" intervals the latter of which coincide with said relay winding connections, each of said track sections having at the opposite end thereof another code following track relay and code repeating means having contacts normally connecting the rails of the associated section to the winding of the said other track relay and which contacts when operated disconnect such relay from the rails and connect to such rails a source of energy, each of said sections having two decoding relays one for the first-mentioned and the other for the other track relay of the associated section and each decoding relay controlled by its associated track relay to detect a code operation of such relay, two slow acting repeater relays at said intermediate location, a first repeater relay for the decoding relay of the first track relay associated with the adjacent end of one of the two adjoining track sections and a second repeater relay for the decoding relay of the other track relay associated with the adjacent end of the other of the two adjoining track sections, two stick relays at said intermediate location, one stick relay for each repeater relay, an energizing circuit for each repeater relay comprising a front contact of its associated decoding relay and a back contact of the other stick relay, a pick-up circuit for each stick relay comprising a back contact of the other stick relay and a back contact of the other repeater relay and a front contact of its associated repeater relay, a stick circuit for each stick relay comprising its own front contact and a back contact of the associated decoding relay, code generating means associated with each of said other track relays and normally responsive to the operation of the associated relay for operating its associated code repeating means at a rate corresponding to the rate of operation of the said associated relay, means controlled by the repeater relay of the first track relay associated with one of two adjacent sections for rendering ineffective the code generating means of the other of said two adjoining sections, means controlled by the repeater relay of the other track relay of the said other section for controlling the code rate at which said coding means codes said track circuit energy supplied to the said one section, and means controlled by the repeater relay of the said other section for at times causing said coding means to operate the said code repeating means of its associated track relay.

13. Apparatus for use at an intermediate loca-

tion in an absolute permissive block railway signal system, said location being defined by the adjacent ends of two adjoining track sections, each of said sections having at one end thereof a source of trackway energy and a code following track relay and coding means operating contacts to repeatedly connect the rails of the associated section first to said source and then to the winding of the said track relay for producing in such section coded track circuit energy consisting of alternate "on" and "off" intervals the latter of which coincide with said relay winding connections, each of said track sections having at the opposite end thereof another code following track relay and code repeating means having contacts normally connecting the rails of the associated section to the winding of the said other track relay and which contacts when operated disconnect such relay from the rails and connect to such rails a source of energy, two decoding relays at said intermediate location a first for the first-mentioned track relay at the adjacent end of one of said two adjoining sections and the second for the other track relay at the adjacent end of the other of said two adjoining sections, two stick relays at said intermediate location one for each decoding relay and each adapted to be picked up when its associated decoding relay is the second of the two to be released, each stick relay being adapted to be held energized over a stick circuit when its associated decoding relay is released, circuit means for normally operating the code repeating means at such location in response to each release of the associated other track relay at such location, said circuit means being controlled by said first decoding relay for at times rendering said circuit means ineffective and also being controlled by the stick relay associated with said first decoding relay for at times preventing said first decoding relay from rendering ineffective such circuit means, said circuit means further being controlled by the said second decoding relay and including means rendered effective when said second decoding relay is released for causing operation of said code repeating device in response to said coding means at such location.

14. In combination, a stretch of two-direction running railway track, a track section included in said stretch, master code equipment located at a given end of said section and effective to supply the section rails with master code energy in the form of recurring "on" period pulses that are separated by "off" period intervals, feed back apparatus located at the opposite end of said section and operable when and only when said master code pulses are there received further to supply the section rails with feed back energy in the form of pulses that recur in step with the "off" periods of the received master code, supplemental equipment also at said opposite section end which comes into operation only when said feed back apparatus is maintained inactive by failure of said master pulses to be transmitted to that opposite end and which then supplies those rails with special code energy in the form of recurring pulses that have no regular time coincidence with the aforesaid master code "off" periods, and means effective under certain predetermined conditions of said stretch for supplying one of said two section ends with a pulse of steady energy which has a duration sufficient to span a full "off" period of the coded energy then being impressed upon the other section end and

which during said "off" period gets through to said other end without interference.

15. In combination, a stretch of two-direction running railway track, a track section included in said stretch, master code equipment located at a given end of said section and effective to supply the section rails with master code energy in the form of recurring "on" period pulses that are separated by "off" period intervals, feed back apparatus located at the opposite end of said section and operable when and only when said master code pulses are there received further to supply the section rails with feed back energy in the form of pulses that recur in step with the "off" periods of the received master code, supplemental equipment also at said opposite section end which comes into operation only when said feed back apparatus is maintained inactive by failure of said master pulses to be transmitted to that opposite end and which then supplies the section rails with special code energy in the form of recurring pulses that have no regular time coincidence with the aforesaid master code "off" periods, and means located at said given section end and rendered effective under certain predetermined conditions of said stretch for supplying said given end with a prolonged pulse of track-way energy which spans a full "off" period of the coded energy then being impressed upon said opposite section end and which during said period gets through to said opposite end without interference following removal of a shunt from the section rails.

16. In combination, a stretch of two-direction running railway track, a track section included in said stretch, master code equipment located at a given end of said section and effective to supply the section rails with master code energy in the form of recurring "on" period pulses that are separated by "off" period intervals, feed back apparatus located at the opposite end of said section and operable when and only when said master code pulses are there received further to supply the section rails with feed back energy in the form of pulses that recur in step with the "off" periods of the received master code, supplemental equipment also at said opposite section end which comes into operation only when said feed back apparatus is maintained inactive by failure of said master pulses to be transmitted to that opposite end and which then supplies the section rails with special code energy in the form of recurring pulses that have no regular time coincidence with the aforesaid master code "off" periods, a relay at said given section end which responds to predetermined changes in the traffic conditions of said stretch, and means rendered effective by each of said relay responses for supplying said given section end with a prolonged pulse of track-way energy which spans a full "off" period of the coded energy then being impressed upon said opposite section end and which during said "off" period gets through to said opposite end and there positively conditions said feed back apparatus for its normal form of vacant section operation.

17. In combination, a stretch of two-direction running railway track, a track section included in said stretch, master code equipment located at a given end of said section and effective to supply the section rails with master code energy in the form of recurring "on" period pulses that are separated by "off" period intervals, feed back apparatus located at the opposite end of said section and operable when and only when said

master code pulses are there received further to supply the section rails with feed back energy in the form of pulses that recur in step with the "off" periods of the received master code, supplemental equipment also at said opposite section end which comes into operation only when said feed back apparatus is maintained inactive by failure of said master pulses to be transmitted to that opposite end and which then supplies the section rails with special code energy in the form of recurring pulses that have no regular time coincidence with the aforesaid master code "off" periods, a relay at said given section end which responds to the initial reception at that given end of said special code energy that gets through thereto following removal of a shunt from the section rails, and means rendered effective by each of said relay responses for supplying the section rails with a prolonged pulse of master energy which spans a full "off" period of said received special code and which during said period gets through to said opposite section end and there positively restores said feed back apparatus to its normal condition of vacant section operation.

18. In combination, a stretch of two-direction running railway track, a track section included in said stretch, master code equipment located at a given end of said section and effective to supply the section rails with master code energy in the form of recurring "on" period pulses that are separated by "off" period intervals, feed back apparatus located at the opposite end of said section and operable when and only when said master code pulses are there received further to supply the section rails with feed back energy in the form of pulses that recur in step with the "off" periods of the received master code, supplemental equipment also at said opposite section end which comes into operation only when said feed back apparatus is maintained inactive by failure of said master pulses to be transmitted to that opposite end and which then supplies the section rails with special code energy in the form of recurring pulses that have no regular time coincidence with the aforesaid master code "off" periods, a normally released relay installed at said given section end and provided with a pick-up circuit which upon each initial reception of said special code energy at that given end is completed for a time sufficient to span a full "off" period of said received code, and means governed by said relay and effective during each picked up condition thereof for supplying said section rails with steady energy which during one of said received code "off" periods gets through to said opposite section end and there positively conditions said feed back apparatus for its normal form of vacant section operation.

19. In combination, a stretch of two-direction running railway track, a track section included in said stretch, master equipment at a given end of said section operated by a master coding contact over a driving connection therewith and effective to supply the section rails with master code energy in the form of recurring "on" period pulses that are separated by "off" period intervals, feed back apparatus at the opposite end of said section driven by the there received pulses of said master code energy and operable during and only during said master pulse reception further to supply the section rails with feed back

energy in the form of pulses that recur in step with the "off" periods of the received master code, supplemental equipment also at said opposite section end operated by an independent coding contact over a driving connection therewith and effective only when said feed back apparatus is inactive still further to supply the section rails with special code energy in the form of recurring pulses that have no regular time coincidence with the aforesaid master code "off" periods, a normally released relay installed at said given section end and provided with a pick-up circuit which upon predetermined changes in the traffic conditions of said stretch is completed for a time sufficient to span a full "off" period of the coded energy then being impressed upon said opposite section end, and means governed by said given end relay and effective during each picked up condition thereof for supplying said section rails with steady energy which during one of the "off" periods of said opposite end code gets through to said opposite section end and there positively conditions said feed back apparatus for its normal form of vacant section operation.

20. In combination, a stretch of two-direction running railway track, adjoining first and second track sections included in said stretch, master code equipment located at the junction of said first and second sections and effective to supply the second section rails with master code energy in the form of recurring "on" period pulses that are separated by "off" period intervals, feed back apparatus located at the remote end of said second section and operable when and only when said master code pulses are there received further to supply the second section rails with feed back energy in the form of pulses that recur in step with the "off" periods of the received master code, supplemental equipment also at the remote end of said second section which comes into operation only when said feed back equipment is maintained inactive by failure of said master energy to reach the equipment location and which then supplies the second section rails with special code energy in the form of recurring pulses that have no regular time coincidence with the aforesaid master code "off" periods, means for interrupting said second section master code energy supply when a shunt is placed across the rails of said first section, and means effective upon removal of said first section rail shunt for supplying the junction end of said second section with a prolonged pulse of trackway energy which spans a full "off" period of the coded energy then being impressed upon said second section's remote end and which during said period gets through to said remote end and there positively conditions said feed back apparatus for its normal form of vacant section operation.

21. In combination, a stretch of two-direction running railway track, adjoining first and second track sections included in said stretch, master code equipment located at the junction of said first and second sections and effective to supply the second section rails with master code energy in the form of recurring "on" period pulses that are separated by "off" period intervals, feed back apparatus located at the remote end of said second section and operable when and only when said master code pulses are there received further to supply the second section rails with feed back energy in the form of pulses that recur in step with the "off" periods of the received master code, supplemental equipment also at the remote end

of said second section which comes into operation only when said feed back equipment is maintained inactive by failure of said master energy to reach the equipment location and which then supplies the second section rails with special code energy in the form of recurring pulses that have no regular time coincidence with the aforesaid master code "off" periods, means for interrupting said second section master code energy supply when a shunt is placed across the rails of said first section, a normally released relay installed at the junction end of said second section and provided with a pick-up circuit which upon a removal of said shunt from the first section rails is completed for a time sufficient to span a full "off" period of the coded energy then being impressed upon said second section's remote end, and means governed by said junction end relay and effective during each picked up condition thereof for supplying said second section rails with steady energy which during one of the "off" periods of said remote end code gets through to said second section's remote end and there positively conditions said feed back apparatus for its normal form of vacant section operation.

22. In combination, a stretch of two-direction running railway track, adjoining first and second track sections included in said stretch, master code equipment located at the junction of said first and second sections and effective to supply the second section rails with master code energy in the form of recurring "on" period pulses that are separated by "off" period intervals, feed back apparatus located at the remote end of said second section and operable when and only when said master code pulses are there received further to supply the second section rails with feed back energy in the form of pulses that recur in step with the "off" periods of the received master code, supplemental equipment also at the remote end of said second section which comes into operation only when said feed back equipment is maintained inactive by failure of said master energy to reach the equipment location and which then supplies the second section rails with special code energy in the form of recurring pulses that have no regular time coincidence with the aforesaid master code "off" periods, means for interrupting said second section master code energy supply when a shunt is placed across the rails of said first section, a relay at the junction end of said second section which responds to a removal of said shunt from the first section rails, and means rendered effective by each of said relay responses for supplying said second section rails with a prolonged pulse of master energy which spans a full "off" period of the said special code energy that is impressed upon said second section's remote end and which during said period gets through to said remote end and there positively restores said feed back apparatus to its normal condition of vacant section operation.

23. In a coded railway signaling system, in combination, a stretch of railroad track having a pair of track rails over which traffic moves in both directions, the rails of the track stretch being divided by insulated joints into a plurality of track sections including a detector section having at one side thereof a first section and at the other side thereof a second section, means for supplying to the rails of said detector section coded detector energy, and means governed by energy supplied over the rails of said detector section and controlling the supply of coded

detector energy to said section rails and also controlling supply circuits for supplying energy to the rails of said detector section, said means being effective when said detector section is occupied to cut off the supply of coded detector energy to the detector section rails, said means being effective on entrance of a train into the detector section from the first section to establish a supply circuit governed by traffic conditions in the second section and being effective on entrance of a train into the detector section from the second section to establish a supply circuit governed by traffic conditions in the first section.

24. In a coded railway signaling system, in combination, a stretch of railroad track having a pair of track rails over which traffic moves in both directions, the rails of the track stretch being divided by insulated joints into a plurality of track sections including a detector section having at one side thereof a first section and at the other side thereof a second section, means for supplying to the rails of said detector section coded detector energy, and means governed by energy supplied over the rails of said detector section and controlling the supply of coded detector energy to said section rails and also controlling supply circuits for supplying energy to the rails of said detector section, said means being effective when said detector section is occupied to cut off the supply of coded detector energy to the detector section rails, said means being effective on entrance of a train into the detector section from the first section to establish a supply circuit governed by traffic conditions in the second section for supplying energy to the detector section rails at the end of the section adjacent said second section and being effective on entrance of a train into the detector section from the second section to establish a supply circuit governed by traffic conditions in the first section for supplying energy to the detector section rails at the end of the section adjacent said first section.

25. In a coded railway signaling system, in combination, a stretch of railway track having a pair of track rails over which traffic moves in both directions, the rails of the track stretch being divided by insulated joints into a plurality of successive track sections including a detector section having at one side thereof a first section and at the other side thereof a second section, said detector section including a track switch having a normal position in which it directs traffic to continue on the main track and a reverse position in which it directs traffic to move between the main track and a branch track, means for supplying to the detector section rails coded detector energy, a first supply circuit governed by traffic conditions in said first track section for supplying energy to the rails of the detector section, a second supply circuit governed by traffic conditions in said second track section for supplying energy to the rails of the detector section, means governed by energy supplied over the detector section rails and controlling the supply of coded detector energy to the section rails and also controlling said first and second supply circuits, said means being effective when the detector section is occupied to cut off the supply of coded detector energy to the section rails, said means being effective on entrance of a train into the detector section from the first section to establish the second supply circuit provided the switch is in its normal position, said means being effec-

tive on entrance of a train into the detector section from the second section to establish said first supply circuit.

26. In a coded railway signaling system, in combination, a stretch of railway track having a pair of track rails over which traffic moves in both directions, the rails of the track stretch being divided by insulated joints into a plurality of successive track sections including a detector section having at one side thereof a first section and at the other side thereof a second section, said detector section including a track switch having a normal position in which it directs traffic to continue on the main track and a reverse position in which it directs traffic to move between the main track and a branch track, means for supplying to the detector section rails coded detector energy, a first supply circuit governed by traffic conditions in the second section for supplying energy to the detector section rails at the end of the detector section adjacent said second section, a second supply circuit governed by traffic conditions in the first section for supplying energy to the detector section rails at the end of the detector section adjacent said first section, means governed by energy supplied over the detector section rails and controlling the supply of coded detector energy to the section rails and also controlling said first and second supply circuits, said means being effective when the detector section is occupied to cut off the supply of coded detector energy to the section rails, said means being effective on entrance of a train into the detector section from the first section to establish the second supply circuit provided the switch is in its normal position and being effective on entrance of a train into the detector section from the second section to establish said first supply circuit.

27. In a coded railway signaling system, in combination, a stretch of railway track having a pair of track rails over which traffic moves in both directions, the rails of the track stretch being divided by insulated joints into a plurality of successive track sections including a detector section having at one side thereof a first section and at the other side thereof a second section, said detector section including a track switch facing the first section and having a normal position in which it directs traffic to continue on the main track and a reverse position in which it directs traffic to move between the main track and a branch track, means for supplying to the detector section rails coded detector energy, a first supply circuit governed by traffic conditions in said first track section for supplying energy to said detector section rails, a second supply circuit governed by traffic conditions in said second track section for supplying energy to said detector section rails, a slow releasing control relay energized when and only when the detector section is vacant and the switch occupies its normal position, a directional relay, a pick-up circuit for supplying energy to said directional relay, said pick-up circuit being complete when the first and detector sections are occupied and said control relay contacts are picked up, said directional relay when energized establishing a stick circuit to maintain itself energized as long as the detector section is occupied, and means governed by energy supplied over the detector section rails and controlling the supply of coded detector energy to the section rails and also controlling said first

and second supply circuits, said means being effective when the detector section is occupied to cut off the supply of coded detector energy to the section rails, said means being effective on entrance of a train into the detector section from said first section to establish said second supply circuit providing said directional relay picks up, said means being effective on entrance of a train into the detector section from the second section to establish the first supply circuit.

28. In a coded railway signaling system, in combination, a stretch of railway track having a pair of track rails over which traffic moves in both directions, the rails of the track stretch being divided by insulated joints into a plurality of successive track sections including a detector section having at one side thereof a first section and at the other side thereof a second section, said detector section including a track switch facing the first section and having a normal position in which it directs traffic to continue on the main track and a reverse position in which it directs traffic to move between the main track and a branch track, a track relay governed by energy supplied over the detector section rails, a slow releasing control relay energized when and only when the track relay is picked up and the switch is in its normal position, a directional relay, a pick-up circuit for said directional relay, said pick-up circuit being complete when the first section is occupied, the detector section track relay is released and the control relay contacts are picked up, said directional relay when energized establishing a circuit to maintain itself energized as long as the detector section track relay is released, the detector section track relay being effective when picked up to establish a circuit to supply coded detector energy to the detector section rails, the detector section track relay being effective when released provided said directional relay is picked up to establish a circuit to supply to the detector section rails energy selected in accordance with traffic conditions in said second section, said track relay being effective when released provided the directional relay is also released to establish a circuit to

supply to the detector section rails energy selected in accordance with traffic conditions in said first section.

29. In a coded railway signaling system, in combination, a stretch of railway track having a pair of track rails over which traffic moves in both directions, the rails of the track stretch being divided by insulated joints into a plurality of successive track sections including a detector section having at one side thereof a first section and at the other side thereof a second section, said detector section including a track switch facing the first section and having a normal position in which it directs traffic to continue on the main track and a reverse position in which it directs traffic to move between the main track and a branch track, a track relay governed by energy supplied over the detector section rails, a slow releasing control relay energized when and only when said track relay is picked up and the switch is in its normal position, a directional relay, a pick-up circuit for said directional relay, said pick-up circuit being complete when the first section is occupied, the detector section track relay is released and the control relay contacts are picked up, said directional relay when energized establishing a circuit to maintain itself energized as long as the detector section track relay is released, the detector section track relay being effective when picked up to establish a circuit to supply coded detector energy to the detector section rails, the detector section track relay being effective when released provided the directional relay is picked up to establish a circuit to supply to the detector section rails at the end of the detector section adjacent said second section energy selected in accordance with traffic conditions in said second section, said track relay being effective when released provided the directional relay is also released to establish a circuit to supply to the detector section rails at the end of the detector section adjacent said first section energy selected in accordance with traffic conditions in said first section.
